4 Claims. (Cl. 246—33)

Our invention relates to a railway signaling system of the absolute permissive block type (A.P.B.) which controls movement of traffic in both directions over a stretch of single track railway. Particularly, our invention relates to an A.P.B. system incorporating coded track circuits to eliminate the use of line wires for control purposes.

Economy in installation, apparatus, and maintenance is desirable in any railway signaling system provided that this economy may be obtained without the sacrifice of any safety features or characteristics. The major expense in many A.P.B. systems has been the line wire necessary for control circuits and the maintenance of these line circuits. Thus coded track circuits, as known today, provide an advantage by requiring no line wires, especially when such coded track circuits utilize both master (normal) and feedback (reverse) codes. In the past, the power requirements of such a coded track system have sometimes been considered excessive, especially where commercial power is not readily available. This heavy power requirement is due principally to the well-known electrical resonance type decoding circuits. However, the development and use of relays of the code following type with mechanically tuned, frequency responsive contacts eliminates much of this heavy power drain. Such relays may be of the general type disclosed and claimed in Letters Patent of the United States 2,730,592, granted in January 10, 1956, to Andrew Hufnagel for a Code Following Relay With Frequency Decoding Contacts. In addition to these relays, the reduction in the amount of apparatus used presents another means of economizing in such signal systems.

With the utilization of longer track circuits and the elimination of line wire control for A.P.B. signal systems, it is desirable and, in fact, still necessary, to retain all of the usual safety factors associated with such systems. One such safety factor is the assurance that the energization and pickup of the directional stick relays at intermediate signal locations in the single track stretch occurs only when a train passes the signal. This type of control for directional stick relays is frequently termed "advance pickup." This feature provides overrun protection at the signals, hand-throw switch protection, and the display of the most restrictive, i.e., stop, indication by each opposing signal immediately behind a train. This particular safety factor is easily provided in line wire signal systems, but has not always been provided in coded track systems.

It is, therefore, an object of our invention to provide a coded track A.P.B. signal system for single track railways using no line wires.

Another object of our invention is to provide a continuously energized, coded track A.P.B. signal system using master and feedback codes.

A further object of our invention is to provide a coded track A.P.B. signal system using mechanically tuned, frequency responsive decoding apparatus.

Another object of our invention is to provide an im-

2

proved coded track A.P.B. system using less apparatus and with greatly reduced power requirements.

It is also an object of our invention to provide, in such a signal system, the feature of advance pickup of the directional stick relays.

Still another object of our invention is to provide a coded track, non-line wire A.P.B. signal system which embodies all the safety features or characteristics usually associated with similar signal systems using line wire control circuits.

Other objects and features of our invention will become apparent as the specification proceeds when taken in connection with the accompanying drawings.

Referring to the drawings,

15 Figs. 1A to 1E, inclusive, when placed adjacent in order from left to right with Fig. 1A at the left, show diagrammatically one form of apparatus embodying our invention, as used in the A.P.B. signal system for a particular stretch of single track.

20 Fig. 2 of the drawings provides a signal control limit diagram for the single track stretch and also includes indications of the coded energy normally in the track circuits.

25 Similar reference characters refer to similar parts of the apparatus in each of the drawings.

30 In practicing our invention, signal controls are transmitted over the rails of the single track stretch by the use of coded track circuits. A neutral master (normal) frequency code is used to control the wayside signals generally in one direction and polar feedback (reverse) code is used to control the wayside signals generally in the opposite direction. However, some variation in the direction of flow of the track codes is necessary between the various track sections formed in the single track stretch between adjacent stations. Within any one particular track section, the master code always flows in one direction and the reverse code in the opposite direction. The signal controls transmitted through these coded track circuits are obtained by mechanically tuned frequency responsive decoding of the master or frequency code using, as an example, the code following relay disclosed in the previously mentioned Hufnagel patent. Non-tuned relay decoding is used for the polar reverse code to obtain the signal controls for the opposite direction in that particular track circuit.

45 Advance pickup control for the directional stick relays using two-track-circuit pickup is provided at the intermediate signals in the single track stretches. In this type of control, each directional stick relay can only be energized due to the occupancy of the adjacent track sections as a train passes the signal in the direction for which that relay is designated. This advance pickup of the directional stick relays is obtained either by the use of two series approach relays, one in each adjacent track circuit, or by the combination of a single series approach relay in one circuit and the code detecting relay for the frequency track code in the other circuit. The directional stick relay circuits provide operation and protection identical with that provided by any of the well-known systems using non-coded track circuits and line wire control circuits. In other words, the present invention provides equivalent operation and protection when hand switches are thrown or if signals are overrun and assures that each opposing signal displays its most restrictive aspect immediately behind each train movement.

60 Referring now to Figs. 1A to 1E of the drawings, when placed adjacent in order from left to right with Fig. 1A at the left, an A.P.B. signal system is shown for a stretch of single track railway extending between stations X and Z. In the remainder of this description,

the direction from X to Z will be considered the eastbound direction. It is to be noted that the same stretch of single track plus some extension at both ends is also shown in Fig. 2 which will be discussed in greater detail hereinafter. At each of the stations X and Z, there is provided a passing siding for the purpose of making meets between opposing trains or passes by trains in the same direction. The eastern end of the passing track at station X is connected to the main track over switch 11W while the western end of the similar siding at station Z is connected to the main track over switch 5W.

In each of the drawings, the single track as well as the passing tracks are shown by the conventional single line symbol. This stretch of track is divided into track sections which are separated electrically from each other by the usual insulated joints which are shown as short heavy lines at right angles to the track symbol. Each of these track sections is designated by the reference character T with a prefix in accordance with the signals at each end of the section. Where possible, the numerical prefix is in accordance with the opposing signals governing movements in opposite directions into the particular track section in question. It will be noted that each insulated joint as shown in the parts of Fig. 1 is either a double or a single signal location. It is to be understood that other insulated joints may be used to provide what are known as cut sections for the purpose of repeating the track circuit energy. However, such cut sections are not shown in this application as they are not necessary for an understanding or a showing of the circuits of our invention.

Each of the signals is indicated by the reference character G with a numerical prefix ascending in order from the eastern end to the western end of the stretch. As shown, signals 6G, 8G, 10G, and 12G control eastbound traffic while signals 5G, 7G, 9G, and 11G control westbound traffic in the single track stretch. Signals 5G and 12G are further termed as station-leaving or head-block signals while signals 6G and 11G are likewise known as home or station-entering signals. All other signals shown in any part of Fig. 1 are intermediate signals. The signals may be of any well known type but are here shown for simplicity as the color-light type. Each signal is thus provided with three lamps, green, yellow, and red, referenced respectively as G, Y and R. In each signal, a single lamp will be lighted to provide a signal aspect, the indications resulting from the green, yellow, and red aspects being, respectively, clear, approach, and stop. The track locations of these signals are indicated adjacent the track symbol by conventional three position semaphore symbols, each track-side symbol being connected by a dotted line to the corresponding lamp group where the signal control circuits are shown. It is to be further noted that, in the semaphore symbol shown adjacent the track symbol, the normal aspect displayed by each signal is indicated by a heavy line in the corresponding position.

Each signal location is supplied with a local source of direct current energy which may be a battery of the proper size and capacity. For simplicity, such energy sources are not shown in the drawings, but only the positive and negative terminals thereof are indicated by the references B and N, respectively.

Certain relays used in the system are of the slow-release type, this characteristic being provided by the relay construction and/or by snubbing circuits connected in multiple with the relay winding. The contacts of such relays are designated as being slow release by downward pointing arrows drawn vertically through the movable portion of each relay contact. Other relays in the system are of the biased type and are so indicated by a horizontal arrow within the symbol for the relay winding. Track relay 12TR (Fig. 1A) is an example of a biased relay. Such relays are so designed that they will be energized properly to close front contacts only when

the flow of current in the relay winding is in the direction of the previously mentioned arrow. Current flow in the opposite direction or deenergizing the relay results in the closing of back contacts of the relay. The contacts of such biased relays are shown in the conventional horizontal plane.

Some of the biased relays, such as track relay 11TR (Fig. 1A), are provided with two separate and distinct armature structures, termed for convenience the normal and reverse armatures. Each armature is provided with an associated set of contacts whose operation is separate from that of the other set of contacts. Each armature is responsive to current flowing through the relay winding in one direction only, operating to close associated front contacts only under this condition. At all other times, the armatures are biased to close associated back contacts, as in any biased relay. The normal armature of relay 11TR, for example, is responsive only to current flowing through the winding in the direction of the left-hand arrow, designated *n*, within the relay symbol. The reverse armature is responsive only to current flow of the opposite direction, indicated by the second arrow within the relay symbol designated *r*. The contacts associated with the normal armature are designated by a suffix *n* added to the conventional letter references for the contacts. Each contact associated with the reverse armature is identified by the suffix *r* added to the otherwise conventional letter reference for the contact. Each double armature biased relay in the circuit arrangement is shown and referenced in a similar manner. As contacts of these relays are referred to throughout the description, the use of the suffixes *n* and *r* will serve to distinguish between the two sets of contacts. It is to be understood, however, that any of these double armature, biased relays may be replaced by two ordinary biased relays having a single armature each. If used, the windings of the two relays are connected in series so poled that one relay is responsive to current flowing in one direction through the series circuit while the second relay is responsive to current flowing in the opposite direction.

Relays which are used for transmission of the master code into the track rails are of the magnetic stick type, as represented by relay 11CTP shown in Fig. 1A. The contacts of such relays are shown in the vertical plane and the relays are indicated by an arrow in the winding symbol the arrow denoting the direction of current flow which will result in the closing of normal or left-hand contacts. Current flow in the opposite direction results in the closing of right-hand or reverse contacts. Such relays maintain their contacts in the position to which they were last operated when the relay winding becomes deenergized.

Each signal location, except signals 5G and 6G shown in Fig. 1E, is provided with code transmitters which establish the code rates for the master track code. Any type of code transmitter may be used, but for purposes of this description, they are shown and will be considered as being of the relay type which is well known in the art. All such code transmitters are permanently energized, their windings being connected directly between terminals B and N of the source. These code transmitters, thus energized, operate to open and close their contacts at the preestablished code rate. Such code transmitters are designated by the reference character CT with a numerical prefix which indicates the code rate at which that particular transmitter operates. For example, in Fig. 1A, code transmitter 180CT operates to close and open its front and back contacts periodically at the rate of 180 times per minute. Other code transmitters shown have code rates of 120 and 75 operations per minute. Other combinations of code rates may of course be used.

Contacts of the code transmitters, and of other relays which normally follow code, are designated as code following by showing the movable portions as a dotted line 75 in each position to indicate that the contact periodically

operates between the two positions, closing front and back contacts alternately. If a code following relay is normally deenergized and operates to follow coded current only on certain occasions, or if certain contacts of a relay are normally non-responsive to code, the movable portion of such contacts are shown solid in the released position, closing back contacts, the energized or code following position, closing front contacts, being indicated by a dotted symbol.

Each track section in the single track stretch and also the main track portion of the station area is provided with two track circuits. Each of these circuits includes a track battery, a track relay, and one or more sets of coding contacts. Each track battery is designated by the reference character TB with a numerical prefix corresponding to the first opposing signal in advance. For example, the track circuit for section 9-12T originating at the west end of this section is provided with a track battery 12TB, the prefix 12 corresponding to the prefix of signal 12G which is an opposing signal for the direction in which the track circuit operates. Where, because of staggered signals, the first opposing signal is more than one track section away, the track battery for the second circuit has the additional prefix A to differentiate it from the battery of the other track circuit. For example, battery A7TB shown in Fig. 1C is for the eastbound track circuit originating at this location to differentiate it from track battery 7TB in Fig. 1D. Each track relay is designated by the reference character TR, but with a numerical prefix the same as the similarly located track battery. It may also be considered that the prefix of the track relay designates the signal which it directly controls, such as track relay 12TR (Fig. 1A) which controls the indications displayed by signal 12G. Again, the extra prefix A is used when necessary to differentiate between track relays whose circuits operate in series, for example, track relays A8TR and 8TR.

Track section 9-12T, for example, has a first track circuit (master code) which controls eastbound traffic which may be traced from the positive terminal of track battery 9TB in Fig. 1B through the winding of series approach relay 10A, normal contact *a* of code transmitter repeater relay 9CTP, one rail of the track section, the winding of relay 12TR in the direction of the arrow, back contact *a* of reverse code relay 12RC, and the other rail of the track section to the negative terminal of track battery 9TB. At times, front contact *a* of relay 12TR bypasses back contact *a* of relay 12RC in this circuit to hold the track relay energized. The other or reverse code circuit for the same track section which controls westbound traffic may be traced from the positive terminal of track battery 12TB over front contact *a* of distant repeater relay 11DP, one rail of section 9-12T, reverse contact *a* of relay 9CTP, the winding of relay 9TR, the second rail of track section 9-12T, back contact *a* of relay 12TR, front contact *b* of relay 12RC and front contact *b* of relay 11DP to the negative terminal of track battery 12TB. In this track section, and likewise all other sections, the track circuit connections to the rails are shown conventionally in keeping with the conventional symbol used for the track. The positive (+) and negative (-) markings shown adjacent the rail connections at each end of a particular track section indicate the track leads which are connected to the same rail, like markings indicating like rail connections. It will be understood, however, that the actual polarity of these rail connections may be reversed from section to section for increased safety. For purposes of this specification, code pulses will be considered to be of the positive polarity when the positive terminal of the track battery is connected to the rails over the (+) track lead. When the track battery positive terminal is connected to the rails over the (-) track lead, the code pulses have a negative polarity.

Each of the other track sections shown has similar

track circuits which may be traced as desired with reference to the two circuits above described. At the present, however, it is not necessary to trace these circuits as they will be hereinafter discussed in detail. The complete circuits for sections 11-14T and 3-6T, the main track sections at stations X and Z, respectively, are not shown since they do not enter directly into the features of our invention. The portion shown in Fig. 1A for section 11-14T is the end of the track circuits at which the master code is transmitted and the reverse code is received. The apparatus shown in Fig. 1E for section 3-6T represents the end of the track circuits which receives the master code and transmits a reverse code through the track rails. For purposes of an understanding of the track circuits for the station area, Fig. 1A may be placed to the right of 1E and the illustrated portion of track section 3-6T considered to be the remainder of track section 11-14T, or vice versa, so that the complete track circuits are shown. At times in the following description, such a combination will be discussed in order to fully explain the operation of the system.

As previously mentioned, the transmission of the master code in the track circuit for section 9-12T is controlled by contacts of code transmitter repeater relay 9CTP shown in Fig. 1B. This relay is of the magnetic stick type previously described and is controlled to repeat the code operation of one of the code transmitters at this location. It is to be here noted that as a specific illustration for the system of our invention, we have chosen the 180 master code rate to control the green aspect, the 120 code rate to control the yellow aspect and the 75 code rate as a carrier for the reverse code when the signals in the master code direction are at stop. A first circuit for controlling relay 9CTP at the 180 code rate may be traced from terminal B over normal contact *b* and the winding of relay 9CTP, front contact *a* of home relay 10H, and back contact *a* of code transmitter 180CT to terminal N. It is noted that the flow of current through the relay winding in this circuit is opposite to the direction of the arrow so that the relay contacts are operated to close in their reverse positions. When code transmitter 180CT closes front contact *a* in its periodic operation, the circuit then extends from terminal B over back contacts *ar* and *an* of relay 9TR, front contact *a* of code transmitter 180CT, front contact *a* of relay 10H, and the winding and reverse contact *b* of relay 9CTP to terminal N. The flow of current through the relay winding is now in the direction of the arrow and relay 9CTP operates its contacts to close in the normal position. It is obvious from these two circuits that, with front contact *a* of relay 10H closed, relay 9CTP periodically operates its contacts between their normal and reverse positions as the code transmitter 180CT alternately closes its front and back contacts. Back contacts *an* and *ar* of relay 9TR are included in this circuit to assure that each pulse of reverse code, as will be subsequently described, is terminated so that relay 9TR is deenergized before normal contact *a* of relay 9CTP is closed to transmit the succeeding pulse of master code. These back contacts of relay 9TR will be included in each of the code rate control circuits for the code transmitter repeater relay.

Front contact *a* of relay 10H selects the 180 code rate to provide a clear indication on signal 12G since relay 10H is energized only when code is being received at this location from the next signal in advance, that is, when signal 10G is displaying any proceed aspect. Another set of control circuits for relay 9CTP may be traced alternately over normal or reverse contact *b* of the relay, the relay winding, back contact *a* of relay 10H, front contact *b* of directional stick relay 10S, and back contact *a* of code transmitter 120CT to terminal N or front contact *a* of the code transmitter and back contacts *an* and *ar* of relay 9TR to terminal B. This circuit is effective to control relay 9CTP at the 120

code rate to transmit master code of this frequency to allow a yellow aspect to be displayed by signal 12G for a following move. The circuits for controlling relay 9CTP at the 75 code rate are similar but include back contact *a* of relay 16H, back contact *b* of relay 10S, and front or back contact *a* of code transmitter 75CT. As will appear hereinafter, master code of this frequency acts only as a carrier for reverse code transmitted from the location of signal 12G, this signal displaying a stop indication under these conditions.

The reverse code for section 9-12T is controlled by reverse code relay 12RC shown in Fig. 1A at the location of signal 12G. Relay 12RC is periodically energized over front contact *a* of track repeater relay 12TP which, in turn, is periodically energized over front contact *b* of track relay 12TR. It is obvious that, when 12TR is energized by a pulse of master code, relay 12TP is energized and picks up followed by the energization of relay 12RC which picks up shortly thereafter. Similarly, the release of relay 12TR at the end of a master code pulse is followed by the cascaded release of relays 12TP and 12RC in that order. The winding of relay 12RC is snubbed by a resistor to slightly retard its release to improve the reverse code transmission. It is to be noted that, in the beginning of an on-period of a master code pulse, relay 12TR is initially energized over back contact *a* of relay 12RC as previously described. The closing of front contact *a* of relay 12TR provides a stick circuit for this relay, bypassing back contact *a* of the reverse code relay so that, when relay 12RC picks up, relay 12TR is not deenergized until the end of the code pulse. At the beginning of the off-period of the master code, as soon as back contact *a* of relay 12TR closes, the circuit is momentarily closed over this back contact and front contact *b* of relay 12RC to transmit the pulse of reverse code, this second track circuit having been previously described. The polarity of this pulse is determined by the position of relay 11DP which is determined, as will be subsequently described, by the traffic conditions in advance of signal 11G.

The choice of three relays to control the application of the reverse code pulses is influenced by the use, in the present system, of relays with mechanically tuned contacts for decoding the frequency of the master code. The arrangement as shown, Fig. 1A, and as above described, is the most economical relay combination that can be used for generating reverse code pulses and for decoding the frequency code, utilizing the relays having mechanically tuned contacts. In other words, the disclosed arrangement requires the minimum number of relays possible to provide both for generating the reverse code and decoding, by mechanically tuned contacts, the master frequency code.

In the system of our invention, frequency code, which is used for the master code, is decoded by circuits which utilize mechanical resonance in place of the well known electrical resonance circuits formerly used. These mechanically resonance circuits are obtained by relay contacts which are mechanically tuned to a selected code rate so that the contacts follow the code pulses only when the preselected code rate is present. At other code rates, these tuned contacts maintain their back contacts closed. Such relays, as previously mentioned, are disclosed and claimed in the aforementioned Hufnagel patent. In one form of the relay as shown by either relay 12TR or 12TP in Fig. 1A, two non-tuned code following contacts are provided which alternately close front and back contacts during the reception of any code rate. In addition, one mechanically tuned contact having a preselected code rate is provided. Such contacts are conventionally designated in the drawings, as illustrated by contact *c* of relay 12TR, by a line drawn through the terminal of the movable portion of the contact and a numerical designation indicating the code rate to which the contact is tuned. Thus contact *c* of relay 12TR is

tuned to the 180 code rate so that front and back contacts are alternately closed only when the relay is energized by current coded at this rate. As previously described, contacts *a* and *b* operate when relay 12TR is energized at any code rate. Relay 12TP is similar in construction but its contact *c* is tuned to the 120 code rate so that it alternately closes back and front contacts only when the relay is energized by current pulses at the 120 code frequency.

10 The decoding circuits shown in Fig. 1A allow for the decoding of each of the three code rates used herein, that is, 180, 120, and 75 pulses per minute. The reception of 180 code is detected by the distant track repeater relay 12DTFP which is energized over tuned front contact *c* of relay 12TR. As previously mentioned, front contact *c* is closed periodically only when relay 12TR is energized by code pulses at the 180 code rate. Relay 12DTFP is thus periodically energized and is snubbed by a half-wave rectifier unit so that it is sufficiently slow 15 release to bridge the open-circuit time of front contact *c* of relay 12TR. During the reception of 180 code, the code detecting relay 12CD is also energized. During the off-period of each code cycle, capacitor C1 is charged from terminal B over back contact *c* of relay 12TR, back 20 contacts *c* and *b* of relay 12TP, the latter contact being non-tuned, and through capacitor C1 and resistor R1 to terminal N. Since relay 12TP repeats the operation of relay 12TR, its front contact *b* will be closed during the on-period of the code cycle for any code rate. At this 25 time, relay 12CD is energized, by the charge stored in capacitor C1, over front contact *b* of relay 12TP in an obvious manner. The half-wave rectifier connected in multiple with the relay winding provides sufficient slow release time so that relay 12CD likewise remains picked up with its front contacts closed during the off-period of the code cycle. This arrangement for energizing relay 12CD assures that each of the tuned relay contacts is properly operating before the capacitor can be charged and subsequently energize the relay. Home relay 12H is steadily energized by a circuit including front contact *a* of relay 12DTFP and front contact *a* of relay 12CD during the reception of master code of the 180 code rate.

If code pulses at the 120 code rate are received by relay 45 12TR and repeated by relay 12TP, relay 12H is energized by a circuit from terminal B over back contact *c* of relay 12TR which remains closed under these conditions, front contact *c* of relay 12TP which periodically closes at the 120 code rate, front contact *a* of relay 12CD and the 50 winding of relay 12H to terminal N. It will be remembered that relay 12CD is energized and picks up during reception of code at any rate. Thus relays 12H and 12CD are energized and pick up during the reception of 120 code. If 75 code rate pulses are received by relay 55 12TR, it is obvious that, under these conditions, only relay 12CD will be energized and pick up to close its front contacts.

It is not necessary to decode master code of the 75 code frequency at intermediate signal locations such as signal 60 8G (Fig. 1C). Thus decoding circuits shown in Fig. 1C for track section 7-8T only detect code of the 180 and the 120 code rates. In this track section, master code at the 75 code rate is used only as a carrier for the reverse code, for reasons to be discussed hereinafter, and has no bearing upon the aspect displayed by signal 8G or upon the code being transmitted into the section to the rear. At signal 12G, it is necessary to decode master code of the 65 75 rate in order to provide overlap control for the eastbound station entering (home) signal 14G, Fig. 2, as will be apparent hereinafter.

Track relay 8TR and its repeater relay 8TP are similar to relays 12TR and 12TP previously discussed. That is, relay 8TR is provided with two code following contacts 75 *a* and *b* which are non-tuned and thus follow any code

rate and with a tuned contact *c* which is mechanically resonant at the 180 code rate and thus responsive only to code pulses at this rate to close its front and back contacts periodically. Relay 8TP has non-tuned contacts *a* and *b* and tuned contact *c* which is responsive only to code of the 120 code rate. However, an additional front contact repeater relay of the track relay is provided at this location for code detection. Relay 8TFP is energized, during the reception of any coded track current over front contact *b* of relay 8TP. Relay 8TFP is made slow release by the capacitor-resistor combination connected in multiple with the relay winding so that it will remain picked up with its front contacts closed during the off-period of the code cycle.

During the reception of master code of the 180 code rate, distant track repeater relay 8DTFP is energized over a circuit including front contact *c* of relay 8TR which is periodically closed under these conditions. Relay 8DTFP is snubbed by a half-wave rectifier and is thus sufficiently slow release to bridge the open circuit time of front contact *c* of relay 8TR. Under the same conditions, home relay 8H (a back contact track repeater) is energized by a circuit including back contact *c* of relay 8TR, back contact *c* of relay 8TP, front contact *a* of relay 8DTFP, front contact *a* of relay 8TFP, and the winding of relay 8H. Relay 8H is provided with a half-wave rectifier snub which is connected in multiple with the relay winding under these conditions, over front contacts *a* in series, of relays 8TFP and 8DTFP. Thus relay 8H, as long as 180 code is being received by relay 8TR, is made sufficiently slow release to bridge the open circuit time of back contact *c* of relay 8TR. As soon as relay 8DTFP or relay 8TFP releases, at which time the supply of coded current is interrupted and the snub removed, relay 8H quickly releases. If master code of the 120 rate is being received, the periodic closing of front contact *c* of relay 8TP energizes home track repeater relay 8HTFP which picks up and remains with its front contacts closed during normal coding action. Under these conditions, relay 8H is energized and the snubbing circuit completed over front contacts *a* of relays 8HTFP and 8TFP. Relay 8H is repeated by a slow release relay 8HP, energized over front contact *c* of relay 8H.

Each of the signal locations at which master code is received by the track relay is provided with one or the other of these two forms of decoding circuits for the frequency code using the mechanically tuned relay contacts to detect the various code rates. Each of these locations will be fully discussed during the description of the system operation hereinafter and will not be further described in detail at the present time.

The polar reverse code of this system is decoded using non-tuned relay circuit arrangements. A specific example is shown in Fig. 1A by the decoding circuits associated with track relay 11TR. The relays in this arrangement are the distant track repeater relay 11DTFP, the home track repeater relay 11HTFP, and the home relay 11H. When positive polarity reverse code is received at this location by relay 11TR, relays 11DTFP and 11H are energized and picked up. The circuit for the former of these two relays is traced from terminal B over front contact *bn* of relay 11TR and the winding of relay 11DTFP to terminal N. This latter relay is energized periodically each time front contact *bn* of the track relay closes and is sufficiently snubbed by the resistor-capacitor combination connected in multiple with its winding to hold its front contacts closed during the off-period of the reverse code. Relay 11H is then energized over a circuit including back contacts *bn* and *br*, in series, of track relay 11TR and front contact *a* of relay 11DTFP. Relay 11H is snubbed by a halfwave rectifier as long as front contact *a* of relay 11DTFP remains closed so that relay 11H is sufficiently slow release to retain its front contacts closed during the open circuit time of the track relay back contacts.

Relay 11HTFP is energized when negative polarity reverse code is received over a circuit including back contact *bn* and front contact *br* of track relay 11TR. Relay 11HTFP is similarly snubbed by a resistor-capacitor combination so that it remains with its front contacts closed during the off-period of the reverse code. Under these conditions, the circuit for relay 11H is completed over front contact *a* of relay 11HTFP. A repeater of the home and distant track repeater relays, relay 11DP, is energized by a circuit traced from terminal B over front contact *a* of relay 11H, front contact *c* of relay 11DTFP, and the winding of relay 11DP to terminal N. Relay 11DP is thus energized when positive reverse code is received by relay 11TR. Relay 11DP, by its contacts *a* and *b*, acts to pole change the reverse code supplied to track section 9-12T.

The decoding circuit arrangements for the reverse code at other locations are similar to that associated with track relay 11TR. As with the circuits used for decoding the frequency code, the arrangements at other locations are modified as necessary to include contacts of directional stick relays, series approach track relays, and others. These modifications and the reasons therefor will be discussed more fully hereinafter in connection with the system operation.

Any A.P.B. signal system uses directional stick relays to establish the direction of traffic for following train moves. Such directional stick relays are usually provided only at intermediate signal locations, one being associated with each signal for a particular direction of traffic and becoming energized upon the passage of a train past that signal in the controlled direction. The system of our invention requires the simultaneous occupancy of the track section to the rear of the signal (the section in approach to the signal) and the track section in advance of the signal in order to energize the associated stick relay. Two forms of circuit arrangement to accomplish this energization of the stick relays are necessary. The first method for energizing the directional stick relay utilizes a series approach relay for the track section to the rear of the signal and a series approach relay for the section in advance of the signal. Each of these relays must be energized and pick up before the stick relay can be energized. The second form requires that a series approach relay in the track circuit to the rear of the signal be energized and a code detecting relay for the section in advance of the signal be deenergized before the stick relay is energized. In each of these forms, it is obvious that the track section to the rear and the track section in advance must be occupied for the required conditions to be in effect. The first form is illustrated in Fig. 1D for westbound traffic at signal 7G. The second form is illustrated at signal location 8G in Fig. 1C. Each form of the circuit arrangement will be discussed in detail in the following paragraphs.

Referring now to Fig. 1D, westbound signal 7G is one of a staggered pair of intermediate signals, 7G and 8G. At this location, reverse code is received from the west through the rails of track section 7-8T from the apparatus associated with signal 8G. In track section 5-7T to the east, that is, to the rear of signal 7G, master code is transmitted from this location to the headblock signal 5G and reverse code is received from the east. Master code is, of course, transmitted west through the rails of section 7-8T in accordance with the traffic conditions to the east. Thus, master code is transmitted in both directions from this signal location. Inserted in the track circuit for the master code in section 5-7T is a series approach relay 7A which obviously is in series with track battery A8TB. When section 5-7T is unoccupied by a train, the track current flowing is insufficient to energize relay 7A to pick up its contacts. However, this track circuit is so adjusted that, as a westbound train approaches signal 7G and the track current increases, relay 7A is eventually sufficiently energized to

pick up and close its front contact *a* periodically in accordance with the code rate of the master code. Relay 7A is repeated by relay 7AP which is energized through an obvious circuit including front contact *a* of relay 7A. Relay 7AP is snubbed by the resistor-capacitor arrangement in multiple with its winding so that once it has closed its front contacts, it retains these contacts closed during the off-periods of the master code.

In series with track battery 7TB, which supplies track current to the master code track circuit for section 7-8T, is the series approach relay 7AA. This relay operates in a manner similar to that described for relay 7A so that upon the near approach of a train, sufficient track current flows to operate relay 7AA and it periodically closes its front contact *a* in keeping with the master code rate. The repeater relay 7AAP is energized over front contact *a* of relay 7AA and is snubbed to have sufficient release time that its front contacts remain closed during the off-period of the master code. Each of these series approach relays may be so adjusted that they will begin operation, as a specific example, when an approaching train is within about 2000 feet of the signal location. It is obvious, of course, that when a westbound train passes signal 7G, relay 7AA immediately begins to operate since the train shunt of section 7-8T is in the immediate vicinity of the signal itself.

During the approach of a westbound train through track section 5-7T, master code is supplied at a predetermined rate, in accordance with the indication displayed by signal 7G, to the track circuit. When the train approaches within a short distance of signal 7G, relay 7A is operated by the master code current flowing from track battery A8TB and periodically closes front contact *a* to energize relay 7AP which retains its front contact closed. At this time, with signal 7G displaying a proceed indication, master code at the 75 code rate is transmitted through track section 7-8T and reverse code of a selected polarity is received by relay 7TR. With reverse code being received, relay 7H is energized through the decoding circuits, in a manner previously described, with relay 7DTFP or relay 7HTFP also energized. As the train passes signal 7G and shunts track section 7-8T, relay 7CTP continues to supply coded energy to the rails. This results in the operation of relay 7AA by this coded current which is of sufficient level to operate the 45 relay. The periodic closing of front contact *a* of relay 7AA energizes its repeater relay 7AAP which picks up to close its front contact.

The release of relay 7TR interrupts the decoding circuits as does the opening of back contact *b* of relay 7AAP. However, a momentary circuit is completed to energize directional stick relay 7S at this time. This circuit extends from terminal B at front contact *a* of relay 7AP over front contact *a* of relay 7AAP, front contact *a* of relay 7H, and the winding of relay 7S to terminal N. Relay 7S picks up and closes its front contact *a* to complete an initial stick circuit which bypasses front contact *a* of relay 7H. Relay 7H, of course, is deenergized by the interruption of the decoding arrangement and releases shortly but not before relay 7S picks up. The closing of back contact *a* of relay 7H completes a final stick circuit for the directional stick relay which includes back contact *a* of relay 7H and front contact *a* and the winding of relay 7S. During this energization of relay 7S, front contacts *a* of relays 7AP and 7AAP remain closed for a sufficient time to maintain the initial stick circuit until back contact *a* of relay 7H closes. This initial stick circuit is closed sufficiently long enough to provide a high degree of protection against the failure of the stick relay to pick up and hold, even though the westbound train is very short and moving at high speed. If signal 8G was located at the same place as signal 7G, that is, as a double signal location, a directional stick relay 8S associated with signal 8G would be similarly controlled for an eastbound train movement.

However, with signal 8G located at a separate location, the control of directional stick relay 8S is of the other form. That is to say, relay 8S is energized in response to the energization of a series approach relay 5 for the rear track section and the deenergization of a code detector for the track section in advance of the signal. Referring to Fig. 1C, a circuit may be traced for energizing relay 8S from terminal B at front contact *a* of series approach repeater relay 8AP over back contact *b* of relay 8TFP, front contact *a* of relay 8HP, and the winding of relay 8S to terminal N. Relay 8AP is energized over an obvious circuit including front contact *a* of series approach relay 8A. This latter relay begins to follow the master code current transmitted westward in section 8-10T when an eastbound train approaches within the preselected distance of the signal. Relay 8AP, of course, is snubbed so as to be sufficiently slow release to hold its front contacts closed during the off-period of the master code. Relay 8TFP, which is energized over front contact *b* of relay 8TP, is energized and remains picked up when track relay 8TR is receiving master code of any of the three code rate, as has been previously described. Relay 8TFP thus is responsive to the occupancy of section 7-8T by an eastbound train as soon as it passes signal 8G. In order for the train to proceed, signal 8G must be displaying either a clear or an approach indication so that home relay 8H and its repeater relay 8HP are energized. Thus, at the instant the eastbound train passes signal 8G displaying a proceed indication, relay 8AP will be picked up due to the approach of the train through the rear track section. Track relay front contact repeater 8TFP will release shortly after the occupancy of section 7-8T, but home repeater relay 8HP, which is inherently slow release, will maintain its front contact closed. Thus relay 8S is energized momentarily as soon as the train passes the signal and picks up to close its front contact *a* to complete an initial stick circuit. A final stick circuit is completed when home relay 8HP releases to close its back contact *a*. However, the initial stick circuit provides sufficient energization of the relay so that it will remain up until the final stick circuit is completed.

Referring now to Fig. 1B, we shall discuss the control of the directional stick relays 9S and 10S at this double signal location. Both forms of control are represented by the circuits for these relays. However, special provisions must be made to assure the energization of both series approach relays for the control of relay 9S. It is to be remembered that, under normal conditions, master code is transmitted westward from this signal location through track section 9-12T while reverse code from the headblock signal location 12G is received over the rails of the same track section. In track section 8-10T, master code is received at this location by track relay 10TR while reverse code is transmitted eastward by the operation of reverse code relay 10RC. Series approach relay 10A in series with track battery 9TB in the master code track circuit for the westward track section is thus controlled in the usual manner upon the approach of the train within, as a specific example, 2000 feet of signal 10G. At that time, relay 10A follows the master code pulses, periodically closing its front contact *a* to energize its repeater relay 10AP which picks up and holds its front contact closed because of its slow release characteristics due to the resistor-capacitor snub.

Series approach relay 9A is connected in series with track battery 10TB only when a westbound train occupies track section 8-10T, this circuit being completed by the release of front contact track repeater relay 10TFP. This relay detects the code following operation of the front contacts of track relay 10TR through the operation of the direct (code following) repeater relay 10TP to periodically close its front contact *b*. Relay 10TFP thus detects the reception of any code, being picked up and

holding its front contact closed when relay 10TR operates to follow any code frequency. When track section 8-10T is shunted by a westbound train so that track relay 10TR is deenergized, relay 10TFP releases and its back contact *e* connects relay 9A in series with track battery 10TB. However, under these conditions, with no master code being received at the location of signal 10G, no reverse code is transmitted since relay 10RC is deenergized due to open front contact *a* of relay 10TP. Thus no track current flows through relay 9A unless special provisions are made to provide code transmission from this location eastward through the track section.

A special circuit is therefore provided to energize relay 10RC at the 120 code rate, during the approach of a westbound train, so that series approach relay 9A may be energized. This circuit for relay 10RC may be traced from terminal B over front contact *c* of home relay 9H, which indicates that signal 9G is displaying a proceed indication, back contact *b* of relay 10TFP which is closed when the westbound train occupies the track section, front contact *b* of code transmitter 120CT, which is periodically closed at the 120 code rate, and the winding of relay 10RC to terminal N. Track circuit current is then supplied through a circuit traced from the positive terminal of track battery 10TB, over back contact *e* of relay 10TFP, the winding of relay 9A, and front contact *a* of relay 9H to one rail of the track section, returning from the other end of the section over the other rail of the track section, back contact *a* of relay 10TR, front contact *b* of relay 10RC which at this time is periodically closed at the 120 code rate, and back contact *b* of stick relay 9S to the negative terminal of track battery 10TV. When the westbound train approaches within the preselected distance of signal 9G, relay 9A is sufficiently energized to follow the master code pulses and its repeater relay 9AP is periodically energized over front contact *a* of relay 9A. Relay 9AP, the winding of which is snubbed by a resistor-capacitor combination, holds its front contacts closed as long as relay 9A follows the code pulses.

Directional stick relay 9S is thus energized in the same manner as that previously described for stick relay 7S (at signal 7G), that is, by the energization of a series approach relay for the track section to the rear of the signal and the energization of the series approach relay for the track section in advance of the signal. Thus, at the instant the westbound train passes signal 9G, a circuit is established for energizing directional stick relay 9S which extends from terminal B at back contact *a* of home repeater relay 10HP which is deenergized prior to this time over front contact *a* of relay 9AP, front contact *a* of relay 10AP which closes shortly after the train occupies section 9-12T, front contact *d* of home relay 9H which remains closed for a short interval after track section is occupied, back contact *c* of relay 10S to check that the opposing stick relay is not energized, and the winding of relay 9S to terminal N. Relay 9S picks up to close its front contact *a* which bypasses front contact *d* of relay 9H to establish an initial stick circuit for relay 9S. Upon the subsequent release of relay 9H, the closing of its back contact *d* establishes a final stick circuit for relay 9S including this back contact *d*, front contact *a* of relay 9S, and back contact *c* of relay 10S. This final stick circuit remains effective until relay 9H is again energized upon the reception of reverse code when the train clears section 9-12T.

Directional stick relay 10S is controlled in a manner similar to the control of relay 8S at signal 8G, although the circuit is slightly different in form due to the double signal location. When an eastbound train passes signal 10G displaying a proceed indication, a circuit is established for energizing relay 10S which extends from terminal B over back contact *d* of relay 9H which is released due to the shunting of the reverse code by the eastbound train, front contact *a* of relay 10AP, back contact *c* of relay 10TFP which releases when the train occupies track

section 8-10T, front contact *b* of relay 10HP which is still closed at this time, back contact *a* of relay 9AP, front contact *a* of relay 10HP, back contact *c* of relay 9S, and the winding of relay 10S to terminal N. The contacts of relay 10HP are included in this circuit rather than contacts of home relay 10H because the latter relay will release more quickly due to the interruption of its snub circuit upon the release of relay 10DTFP or relay 10HTFP. Relay 10HP is sufficiently slow release to hold the energizing circuit closed until relay 10S picks up and closes its front contact *a* to complete an initial stick circuit. The final stick circuit of relay 10S may be traced from terminal B over back contact *a* of relay 10HP, front contact *a* of relay 10S, back contact *c* of relay 9S, and the winding of relay 10S to terminal N. The winding of relay 10S is shunted by a resistor to bridge the release transfer time of independent front and back contacts of relay 10HP. This is necessary since front contact *b* of this relay is in the initial stick circuit of relay 10S and will open before back contact *a* can close to complete the final stick circuit.

The apparatus and circuits at the various signal locations, which have thus far been discussed in detail provide a signal system for the stretch of single track having signal control limits as shown in Fig. 2. Referring now to Fig. 2, it is evident that the stretch of track shown extends in each direction beyond the limits of the track shown in the various parts of Fig. 1 taken together. The stretch of track is extended in Fig. 2 for the purpose of better and more simply illustrating the limits of the signal controls which are effective for various types of train movements. The control limits illustrated in a conventional manner above the track diagram by solid and dotted lines are for westbound train movements, that is, are for the signals governing westbound train movements. The similar limits shown below the track diagram are for the signals governing eastbound movements. The signals along the portion of the track in Fig. 2 which corresponds to the track shown in the parts of Fig. 1 bear the same designation in order that correspondence between the two diagrams may be easily established. Each track section is also provided with symbols to indicate the normal code flow during the at-rest condition of the system, that is, when no train occupies any portion of the stretch shown. The symbols used for the signal control limits and for the track code are shown in the legend at the bottom of Fig. 2 and it is believed that they can be completely understood from this legend.

The study of the diagram in Fig. 2 shows that the control of the headblock signals for opposing moves, for the approach and the clear indications, extends to the opposing headblock signal. This same control is also true for the intermediate signals in advance of a headblock signal as far as the opposing headblock signal for a single track stretch. As an example, signal 5G at station Z, which controls westbound moves leaving the station and entering the single track stretch between station Z and station X, is controlled to the stop position when an eastbound train passes signal 12G as is indicated by the signal control limits shown above the track diagram. Until the opposing eastbound train passes signal 12G, signal 5G stands in its clear position. Conversely, signal 12G and also signals 10G and 8G are placed in the stop position when a westbound train passes signal 5G. At the same time station entering signal 14G at the west end of station X is controlled to its approach position, displaying a yellow aspect. Signal 14G is controlled to its stop position displaying a red aspect when the same westbound train passes signal 9G, the distant signal for station X. Similar conditions hold for station entering signal 3G at the east end of station Z, except that this signal is controlled to its stop indication when an eastbound train passes the location of signal 7G rather than signal 8G, signals 7G and 8G being located on a "normal stagger."

For a following move, station entering signal 14G remains in its stop position until the preceding train passes signal 10G at which time signal 14G is controlled directly to its clear position. As shown in Fig. 2, signals 1G and 2G east of station Z are placed in what is generally termed a "reverse stagger." Such location of signals is used depending upon speed restrictions, grades, or other factors to best control the movement of trains. With signals 1G and 2G so located, station entering signal 6G at station Z is controlled to its approach position for a following move when the preceding train passes the location of westbound signal 1G. Signal 6G is not held at stop until that train passes signal 2G, since the controlling factor, for station overlap purposes, is that only the track sections between signal 6G and the second opposing signal in advance must be unoccupied. Signal 6G, however, is controlled to its clear position for a following move only after the preceding train has cleared the second eastbound signal in advance, signal 2G. Other signal control limits and the flow of the various code pulses is obvious from the above discussion and with an inspection of the drawing. Such signal control limits are not unique to the system of our invention and Fig. 2 is provided primarily as an aid to understanding the description of the operation of the system which follows.

We shall now describe the operation of the apparatus in the system of our invention during the movement of an eastbound train and then a westbound train through the stretch of single track shown in the parts of Fig. 1. As shown, the apparatus in Fig. 1 in its entirety is in the normal or at-rest position, that is, the position it assumes when no train is occupying any track section between the stations X and Z, or closely approaching such sections.

For section 9-12T, relay 12TR is following the master code pulses transmitted from the eastern end of the section by relay 9CTP as supplied by track battery 9TB. These code pulses are at the 180 code rate so that relays 12DTFP and 12CD, shown in Fig. 1A, are energized and held picked up due to the coding action of relay 12TR and its repeater relay 12TP through the mechanically tuned frequency responsive contacts of these relays. In addition, relay 12H is energized over front contacts *a* of relays 12DTFP and 12CD and is likewise picked up. Signal 12G is thus displaying a green aspect to give a clear indication to approaching trains. The green lamp G of signal 12G is lighted over the circuit including front contacts *b*, in series, of relays 12H and 12DTFP.

At the same time, transmitting relay 11CTP is energized at the 180 code rate through circuits including normal and reverse contacts *b* of relay 11CTP alternately, front contact *b* of relay 12CD, front contact *a* of relay 12H, and back contact *a* of code transmitter 180CT or front contact *a* of this transmitter and back contacts *an* and *ar* of track relay 11TR. Thus, code pulses at the 180 code rate from track battery 11TB are transmitted west through the main track section 11-14T. At the same time, reverse code pulses of positive polarity are received from the west end of this track section by relay 11TR.

Likewise, relay 12RC is energized periodically at the 180 code rate over front contact *a* of relay 12TP so that reverse code pulses are transmitted eastward through section 9-12T by front contact *b* of relay 12RC, this reverse code being of the positive polarity since relay 11DP is energized and its front contacts *a* and *b* are closed at this time. At the eastern end of section 9-12T, the normal armature of relay 9TR is responsive to the positive polarity reverse code so that its contacts periodically pick up. This results, through the decoding arrangement previously described, in the energization of relays 9DTFP and 9H. This decoding arrangement includes back contact *b* of relay 10AP which is released at this time since relay 10A is not responsive to the coded energy flowing in the track circuit. The circuit for relay

9H also includes back contact *d* of directional stick relay 10S which likewise is closed since no train has passed in an eastbound direction. Signal 9G thus displays a green aspect to provide a clear indication for westbound trains, the circuit for the green lamp G of signal 9G including front contacts *b*, in series, of relays 9H and 9DTFP. It is to be understood that this signal lamp may be approach lighted upon the entry of a westbound train into track section 8-10T in a well known manner, but for simplicity such approach lighting circuits are not shown in the present disclosure.

In section 8-10T, at the west end, track relay 10TR follows code pulses at the 180 code rate transmitted from the east end. At this time, of course, relays 9A, 9AP, 15 and 9S are all deenergized and released. Thus, a circuit is completed over back contacts *d* and *b* of relays 9S and 9AP, respectively, for the decoding arrangement, similar to those previously described, by which relays 10DTFP and 10H are energized and pick up. Signal 10G thus displays a green aspect, its lamp G being energized by a circuit including front contacts *b* of relays 10DTFP and 10H. Relay 10HP, a slow release repeater of relay 10H, is likewise energized since front contact *c* of relay 10H is closed.

20 As previously indicated, relay 10TP follows the code operation of relay 10TR, that is it operates at the 180 code rate, and periodically closes its front contact *b* to energize relay 10TFP which picks up and having slow release characteristics, holds its front contacts closed during the off-period of the code pulses. With relay 9H picked up closing its front contact *c*, and with front contact *b* of relay 10TFP closed, relay 10RC is periodically energized over front contact *a* of relay 10TP and follows the code pulses to transmit, over its front contact *b*, a reverse code of positive polarity through the track rails. Other circuits governing relay 10RC are open at this time.

At the eastern end of the track section at the location of signal 8G, relay A7CTP is operated at the 180 code rate in order to transmit the master code from track battery A7TB. During the off-periods of this master code, the normal armature of track relay A7TR is responsive to the reverse code flowing from the west end of the circuit and operates its contacts accordingly. 45 Relay 8A is nonresponsive to the master code since the track section is unoccupied and thus relay 8AP is deenergized and released. Back contact *b* of relay 8AP completes the connection to the source of energy for the decoding circuit arrangement including contacts *bn* and *br* of relay A7TR and relays A7DTFP and A7H are energized at this time. The circuit for relay A7H checks over back contact *c* of relay 8S to assure that this relay is released. Since this location is only a repeater for the reverse code, that is, the decoding relays do not directly control a signal, a check is included in the circuit for relay A7DTFP and for relay A7HTFP over back contact *c* of the opposite polarity decoding relay to assure that the decoding action is proper. In addition, the capacitor-resistor snub for each relay is connected in multiple with the relay winding only when back contact *c* of the other relay is closed. When a change occurs in the polarity of the received reverse code, the capacitor snub of the released relay is charged by the code following action of the corresponding armature of relay A7TR. For example, if the conditions shown in the drawings change so that negative reverse code is received by relay A7TR, the capacitor snub associated with relay A7HTFP is periodically charged over front contact *br* of the track relay although relay A7HTFP is not energized because back contact *c* of relay A7DTFP is open. When the originally energized relay (A7DTFP in the specific example) releases at the end of its slow release period, the closing of its back contact *c* allows the charge on the capacitor to immediately energize the op-

posite relay (A7HTFP) which quickly picks up. This provides a quick pole changing action of the reverse code repeated into the eastward track section.

In track section 7-8T, relay 7CTP at the eastern end is periodically energized at the 180 code rate through a circuit which is obvious from the inspection of the drawings by considering the previously traced circuits for similar relays. Contact *a* of relay 7CTP transmits pulses of master code at the 180 code rate through the rails of the section so that relay 8TR at the west end follows the code pulses and is repeated in the usual manner by relays 8TP and 8RC. The circuit for relay 8RC is completed over front contact *a* of relay A7H to assure that reverse code is being received through the section to the rear of signal 8G. Relay 8RC periodically closes its front contact *b* to transmit positive polarity reverse code through the rails which the normal armature of relay 7TR at signal location 7G, follows. At the west end of this section, because of the code following action of relays 8TR and 8TP, relays 8TFF, 8DTFP, and 8H are energized through the various decoding circuits and hold front contacts closed, having slow release characteristics due to the snubs on the relay windings. The green lamp G of signal 8G is thus energized over front contacts *b* of relays 8DTFP and 8H and a clear indication is displayed. At the east end, relay 7AA is obviously non-responsive to the master code pulses since the section is unoccupied and, therefore, relay 7AAP is deenergized and in its released position. With back contact *b* of relay 7AAP closed, terminal B is connected to the decoding arrangement for the reverse code and, with positive polarity reverse code pulses being received, relays 7DTFP and 7H are energized and pick up. Signal 7G thus displays a clear indication since its green lamp is energized over the circuit including front contacts *b* of relays 7H and 7DTFP. Both stick relays connected with the two signals, that is, relays 7S and 8S, are deenergized at this time and in their released position. At the west end, relay 8HP, a slow release repeater of home relay 8H, is energized over front contact *c* of relay 8H.

In section 5-7T, the eastern section of the single track stretch, relay A8CTP, shown in Fig. 1D, is periodically energized over the usual circuit arrangement with the 180 code rate being selected over front contact *c* of relay 7H. Coded operation of contact *a* of relay A8CTP transmits master code pulses which relay 5TR at the eastern end of the section follows. This code following operation of relay 5TR causes its repeater relays 5TP and 5RC, each a direct front contact repeater of the preceding relay, to likewise operate at the 180 code rate. The periodic closing of front contact *b* of relay 5RC transmits a reverse code having the positive polarity, as established over front contacts *a* and *b* of relay 6DP, which controls the normal armature of track relay A8TR at the western end of the track section. Since relay 7A is non-operating and relay 7AP thus deenergized, the reverse code decoding arrangement is completed over back contact *b* of relay 7AP and the operation of contact *bn* of relay A8TR periodically energizes relays A8DTFP and A8H so that these relays pick up. The circuit for relay A8H is checked over back contact *c* of stick relay 7S. At the eastern end, the coded operation of the mechanically-tuned, frequency responsive contact *c* of relay 5TR and ordinary contact *b* of relay 5TP results in the energization of relays 5DTFP and 5CD in the usual decoding arrangement. In addition, relay 5H is energized over front contacts *a* of relays 5DTFP and 5CD. Signal 5G thus provides a clear indication for westbound trains, its green lamp being lighted by an obvious circuit including front contacts *b* of relays 5H and 5DTFP.

Relay 6TR is operating at this time to follow code pulses of the 180 code rate received through the rails of section 3-6T from the eastern end. Relays 6TP and 6RC repeat the operation of the track relay, the circuit for relay 6RC being completed over front contact *b* of

relay 5CD to assure that a code is being received from the west. Relay 6RC transmits a positive polarity reverse code by the periodic operation of its front contact *b*. The decoding arrangement for the frequency code received by relay 6TR results in the energization of relays 6DTFP and 6H so that relay 6DP is likewise energized over the circuit including front contact *a* of relay 6H and front contact *c* of relay 6DTFP. Signal 6G displays a clear indication, its green lamp being energized over the circuit including front contacts *b* of relays 6DTFP and 6H.

It is now assumed that an eastbound train passes signal 12G which is displaying a green aspect. The rails of section 9-12T are shunted and relay 12TR is thus de-energized and remains released with its back contacts closed. The decoding relays 12DTFP, 12CD, and 12H all release at the end of their slow release periods, with relay 12H releasing very shortly following the release of relay 12CD since its snub is interrupted by front contact *a* of relay 12CD. Signal 12G is thus controlled to a stop indication, the red lamp being energized over back contact *b* of relay 12H. Relays 12TP and 12RC likewise are deenergized and remain released so that the transmission of reverse code from this location is halted. It is obvious that reverse code pulses would also be shunted by the train occupying the section.

It is apparent from Fig. 2 that the approach of this train toward station X causes changes in the condition of the apparatus associated with the stretch of track between stations X and Z to indicate the approach of the train by changes in signal indications. However, in order to simplify the description, these changes are for the moment ignored and the apparatus considered to be in the at-rest condition in which it was last described. This assumption does not affect the understanding of the operation of the system. As the description progresses, the changes which occur at station X will become apparent from the description of the operation of the apparatus in the vicinity of station Z, particularly the change in the indications displayed by signals 3G and 1G (Fig. 2).

With section 9-12T occupied, relay 9TR is also deenergized and all its contacts remain in their released position. With front contact *bn* of relay 9TR remaining open, decoding relay 9DTFP is deenergized and releases at the end of its slow release period. Relay 9H releases shortly following the release of relay 9DTFP since its energizing circuit and rectifier snub are interrupted by the opening of front contact *a* of relay 9DTFP. Relay 9CTP continues to follow the code transmitter since its operating circuit is not affected by the passage of the train into section 9-12T. In other words, the release of relay 9TR to continuously close its back contacts does not interfere with the operation of code transmitter repeater relay 9CTP. However, the release of relay 9H and the resultant opening of its front contact *c* deenergizes relay 10RC so that it no longer follows the operation of relay 10TP. This halts the transmission of reverse code from this location eastward through track section 8-10T. Release of relay 9H also changes the indication displayed by signal 9G to the stop indication, the red lamp being energized over back contact *b* of relay 9H.

At signal location 8G, the halting of the reverse code in track section 8-10T deenergizes track relay A7TR and its contacts remain in their released position. This results in the release of the decoding relays A7DTFP and A7H. The opening of front contact *a* of relay A7H interrupts the circuit for relay 8RC and this relay no longer follows the code operation of relay 8TP. The deenergization of relay 8RC halts the transmission of the reverse code eastward through section 7-8T and relay 7TR at the east end of this track section is deenergized and releases. At signal location 8G, there is no change in the operation of relay A7CTP so that master code continues to be transmitted westward through track

section 8-19T. With relay 7TR no longer following reverse code, decoding relays 7DTFP and 7H become de-energized and eventually release, opening their front contacts. This controls signal 7G to display the stop indication, the red lamp being energized over back contact *b* of relay 7H.

The release of relay 7H changes the code following operation of relay A8CTP to the 75 code rate. The circuit arrangement for controlling the relay at this rate includes back contacts *an* and *ar* of relay A8TR, front and back contacts *b* of transmitter 75CT, back contact *b* of relay 7S, back contact *c* of relay 7H, the winding of relay A8CTP and its normal and reverse contacts *b*. Reception of master code at the 75 code rate at the east end of track section 5-7T, of course, causes relays 5TR and 5TP to operate at this code rate. Contact *c* of these relays now remain with back contacts closed since each of these contacts is tuned mechanically to be responsive only to higher code frequencies. This causes the release of relay 5DTFP and, when its front contact *a* opens, the release of relay 5H, each of these relays releasing at the end of its slow release period. The release of these relays causes signal 5G to display the stop indication, the red lamp being lighted over back contact *b* of relay 5H. However, relay 5CD remains energized since contact *b* of relay 5TP follows the 75 code rate, alternately closing front and back contacts so that the decoding action using capacitor C2 keeps the relays sufficiently energized to hold its front contact closed. As long as front contact *b* of relay 5CD remains closed, relay 6RC continues to operate to follow the code operation of relay 6TR so that reverse code continues to be transmitted eastward through section 3-6T. However, the opening of contact *a* of relay 5H deenergizes relay 5HP which releases and pole-changes the polarity of the reverse code, the track circuit now being completed over back contacts *a* and *b* of this latter relay.

Relay 5RC continues to follow the code operation of relay 5TP at the 75 code rate, and the periodic closing of its front contact *b* continues to transmit reverse code westward through section 5-7T. This reverse code is, at this time, of positive polarity since relay 6DP remains energized. At the west end, the normal armature of relay A8TR continues to operate to follow the reverse code. The rate of operation of the relay contacts is immaterial and thus there is no change in the energized condition of the decoding relays. Likewise since front contacts *b* and *a* of relays 8SDTFP and 8H remain closed, relay 7CTP continues to follow the 180 code rate.

As has been described, each of the westbound signals 9G, 7G, and 5G now displays a stop indication. Meanwhile, referring to Fig. 2, westbound signals 3G and 1G display a yellow aspect, the approach indication. It has been shown that the reverse code transmitted by relay 6RC at station Z eastward into track section 3-6T is now of the negative polarity due to the release of relay 5HP. Referring to Fig. 1A, it will be seen that, if relay 11TR is energized by negative polarity reverse code so that the reverse armature operates its contacts, relay 11H remains energized, but relay 11HTFP is energized instead of relay 11DTFP since back contact *bn* of relay 11TR remains closed while contact *br* alternately closes front and back contacts. The yellow lamp of signal 11G is then energized over front contact *b* of relay 11H and back contact *b* of relay 11DTFP. At the same time, relay 11DP is deenergized by the opening of front contact *c* of relay 11DTFP so that it releases to pole-change the reverse code transmitted eastward from this location, the track circuit being completed over back contacts *a* and *b* of relay 11DP. At the next signal location to the rear of the westbound signal in the specific example being discussed, relay 9TR, energized by negative polarity pulses, operates the contacts of its reverse armature so that relay 9HTFP is energized instead of relay 9DTFP, relay 9H remaining energized. Signal 9G thus

displays an approach indication, the yellow lamp being energized over an obvious circuit. The action described for signals 11G and 9G, by way of illustration, corresponds to that which happens under the present conditions at signals 3G and 1G so that they display the approach indication previously described.

As the eastbound train approaches signal 10G, relay 10A is sufficiently energized to follow the master code pulses being transmitted westward into section 9-12T. 10 This results in the energization of relay 10AP which picks up and holds its front contacts closed. The opening of back contact *b* of relay 10AP interrupts the energy supply to the decoding circuits for the reverse code at this location. However, relay 9TR is already shunted by 15 the train and has previously ceased operation to deenergize the decoding relays. As the train passes signal 10G, which is displaying the green aspect, track section 8-10T is shunted causing relay 10TR to be deenergized and remain released. When relay 10TR ceases operation, relay 10DTFP is deenergized and eventually releases. The opening of its front contact *a* deenergizes relay 10H which likewise releases. This causes signal 10G to display a stop indication immediately behind the train, in fact, as the train passes. Relay 10TP is also deenergized and halts its code following operation. The opening of front contact *b* of relay 10TP deenergizes relay 10TFP which releases at the end of its slow release period. The circuit is now complete for energizing directional stick relay 10S. This circuit is traced from 30 terminal B at back contact *d* of relay 9H over front contact *a* of relay 10AP, back contact *c* of relay 10TFP, front contact *b* of relay 10HP, back contact *a* of relay 9AP, front contact *a* of relay 10HP, back contact *c* of relay 9S, and the winding of relay 10S to terminal N. 35 The closing of front contact *a* of relay 10S, when it picks up, completes an initial stick circuit bypassing front contact *a* of relay 10HP. The final stick circuit is completed at back contact *a* of relay 10HP when this relay eventually releases, deenergized by the opening of front contact *c* of relay 10H.

A circuit is now complete for controlling relay 9CTP at the 120 code rate. This circuit includes back contact *a* of relay 10H, front contact *b* of relay 10S, and front and back contacts *a* alternately, of transmitter 120CT. 45 When the eastbound train clear section 9-12T, master code at the 120 code rate is immediately transmitted westward through section 9-12T to the location of signal 12G where relay 12TR operates to follow the code pulses. It is to be noted at this time that, with the section unoccupied, relay 10A is inoperative and relay 10AP is thus deenergized. Relays 12TP and 12RC, of course, follow the code operation of relay 12TR. With these relays operating at the 120 code rate, contact *c* of relay 12TR is inoperative but contact *c* of relay 12TP, which 50 is mechanically tuned to be responsive to this code frequency, alternately closes its front and back contacts. This results in the energization of relays 12H and 12CD, both of which pick up and hold their front contacts closed during this coding action. The circuit is established at 55 this time for energizing the yellow lamp of signal 12G, which circuit includes front contact *b* of relay 12H and back contact *b* of relay 12DTFP.

The operation of relay 11CTP, which has been controlled at the 75 code rate until this time is now transferred to the 180 code rate, the circuit being selected over front contact *b* of relay 12CD and front contact *a* of relay 12H. This results in the eastbound signal at the west end of section 11-14T changing from the stop indication to the clear indication, its green lamp being energized. This action corresponds to that indicated by the signal control limits shown in Fig. 2.

The operation of relay 12RC to follow the received master code causes reverse code to be transmitted eastward through section 9-12T. The polarity of this code

is positive since relay 11DP is, at this time, energized due to reverse code being received from the west end of station X. These conditions hold providing there is no following eastbound train, which we shall assume. Relay 9TR is properly energized to operate its normal armature, causing code following action by the corresponding contacts. Relay 9DTFP is energized at this time and picks up, but relay 9H remains released, since the decoding circuit controlling relay 9H is interrupted at back contact *d* of relay 10S which remains energized through its final stick circuit. Signal 9G thus continues to display a stop indication behind the train occupying section 8-10T.

As this eastbound train approaches signal 8G, relay 8A is eventually sufficiently energized to follow the pulses of master code, and as a result, relay 8AP is energized and picks up, holding its front contacts closed. As the train passes signal 8G, it shunts the rails of section 7-8T causing the deenergization of relay 8TR so that it ceases to follow code pulses. Relays 8TP and 8TFP are deenergized in order and both release their contacts. Relays 8DTFP and 8H are deenergized due to the non-operation of relays 8TR and 8TP and these decoding relays shortly release causing signal 8G to change to the stop indication, the red lamp being energized over an obvious circuit. The release of relay 8TFP completes the circuit which was previously traced for energizing directional stick relay 8S and this relay picks up, completing an initial stick circuit at its own front contact *a*. A final stick circuit is completed when relay 8HP eventually releases at the end of its slow release period closing its back contact *a* to complete the circuit including front contact *a* and the winding of relay 8S. This latter relay thus holds energized as long as relay 8HP is deenergized.

With relay 8H released and relay 8S energized, a circuit is complete for controlling transmitter repeater relay A7CTP at the 120 code rate. This circuit arrangement is selected over back contact *a* of relay 8H and front contact *b* of relay 8S and the relay is controlled over front and back contacts *a*, alternately, of transmitter 120CT. Thus, when the train clears section 8-10T, master code at the 120 code rate is transmitted westward to the location of signal 10G. Relay 10TR follows this master code and is repeated directly by the code following operation of relay 10TP. This is followed by the energization of relays 10TFP, 10HTFP, and 10H. Relay 10HTFP is selected since the 120 code operation of relay 10TP permits its contact *c* to be responsive to the code frequency. The circuit is now established for energizing the yellow lamp of signal 10G, the circuit including front contact *b* of relay 10H and back contact *b* of relay 10DTFP, so that this signal displays an approach indication.

The closing of front contact *c* of relay 10H energizes relay 10HP which picks up open its back contact *a*, thus deenergizing directional stick relay 10S which releases at this time since its energizing circuit is open at several points. The release of relay 10S to close its back contact *b* completes the circuit for energizing relay 9H. Since relay 9TR is following the reverse code and relay 9DTFP is already energized so that its front contact *a* is closed, relay 9H picks up. The closing of its front contact *b* completes a circuit over front contact *b* of relay 9DTFP to energize the green lamp of signal 9G and this signal displays a clear indication.

The closing of front contact *c* of relay 9H completes a previously traced circuit to allow relay 10RC to follow the coding action of relay 10TP and reverse code of positive polarity is transmitted eastward through section 8-10T. The positive polarity for the reverse code is selected by front contact *a* of relay 9H and back contact *b* of relay 9S which occupy the named positions at this time. At signal location 8G, the normal armature of relay A7TR follows the positive polarity reverse code. The operation of contact *bn* of relay A7TR periodically

energizes relay A7DTFP which picks up, the circuit also including back contact *c* of relay A7HTFP. Although front contact *a* of relay A7DTFP is closed, relay A7H is not energized since its circuit is open at back contact *c* of relay 8S. Relay 8RC is thus prevented from following any code pulses which might incorrectly be received at this time by relay 8TR.

As the eastbound train nears signal 7G, relay 7AA begins to follow the master code pulses and relay 7AAP is energized and picks up, holding its front contacts closed. As the train passes signal 7G and shunts the rails of section 5-7T, relay 7A immediately follows the master code pulses transmitted by relay A8CTP. This results in the energization of relay 7AP which picks up and remains held up through the coding action. However, even though front contacts *a* of relays 7AP and 7AAP are closed, relay 7S is not energized since its circuit is interrupted at front contact *a* of relay 7H, this relay having released prior to this time. Relay A8TR is deenergized by the train shunting the rails and releases all its contacts. This deenergizes relays A8DTFP and A8H which release. The closing of back contact *a* of relay A8H selects contact *a* of code transmitter 75CT to control relay 7CTP, this circuit also at times including back contacts *an* and *ar* of relay 7TR. Relay A8CTP continues to operate at the 75 code rate since there is no change in the circuit controlling this relay.

The shunt on section 5-7T deenergizes track relay 5TR so that it no longer follows the pulses of code transmitted into the rails by relay A8CTP at the west end of the section. Relay 5TP is likewise deenergized as are relays 5RC and 5CD, the reasons being obvious from an inspection of the drawings. This halts the transmission of reverse code westward into the track section, although of course any code pulses are shunted away from relay A8TR by the train. The opening of front contact *b* of relay 5CD interrupts the circuit for energizing relay 6RC and this relay ceases to follow the code following operation of relay 6TP. This halts the transmission of reverse code eastward in section 3-6T deenergizing a track relay 3TR at the east end of the track section and causing signal 3G (Fig. 2) to change to the stop indication. This action may be more clearly illustrated by considering relay 11TR, shown in Fig. 1A, which is similarly situated to the assumed relay 3TR. If this relay ceases to follow a reverse code, the resulting release of the decoding relays including relay 11H changes the signal aspect to red, the lamp being energized over back contact *b* of relay 11H. However, it will be noted that there is no change in the reverse code being transmitted eastward through the section to the rear of the home signal, since relay 12RC is controlled directly by track repeater relay 12TP and since relay 11DP was previously released so that the reverse code has a negative polarity. Referring again to Fig. 2, it is apparent from the above that signal 1G, the westbound distance signal for station Z, at this time remains at the approach indication.

When the eastbound train clears track section 7-8T, master code pulses are transmitted westward at the 75 code rate by the operation of relay 7CTP. Relay 8TR at the location of signal 8G is responsive to these code pulses to operate its contacts at the same code rate. Relay 8TP follows directly and, as a result of the periodic closing of its front contacts, energizes relay 8TFP which picks up. However, the decoding relay arrangement is nonresponsive, since neither contact *c* of relay 8TR nor contact *c* of relay 8TC operates when the relay is energized at the 75 code rate. Thus relays 8DTFP and 8HTFP are not energized. Even though front contact *a* of relay 8TFP is closed, relay 8H cannot be energized as its circuit is open at front contacts *a* of the other two decoding relays. Relay 8RC also remains deenergized since its circuit is open at front contact *a* of relay A7H which is still deenergized at this time due to open back

contact *c* of stick relay 8S. Thus, there can be no operation of relay 7TR at signal location 7G and likewise there is no change in the present conditions to the rear of signal 8G.

As the train passes signal 6G to enter station Z, it shunts section 3-6T so that relay 6TR is deenergized, followed by the deenergization of relay 6TP. With both of these relays inoperative, that is, not following code, decoding relays 6DTFP and 6H are deenergized and shortly released. The closing of back contact *b* of relay 6H energizes the red lamp of signal 6G and this signal thus is controlled to the stop indication. The opening of front contacts *a* and *c* of relays 6H and 6DTFP, respectively, deenergizes relay 6DP which releases to pole change the connections of track battery 5TB to the track rails.

When the train clears section 5-7T, the master code being transmitted at the 75 code rate from the west end of this section is received by relay 5TR. Its operation is repeated, in order, by relays 5TP and 5RC. The periodic closing of front contact *b* of relay 5RC transmits a reverse code, now of negative polarity, westward through the section to the location of signal 7G. The reverse armature of relay A8TR is responsive to this reverse code and operates to follow the code pulses. The periodic closing of front and back contacts *bc* of relay A8TR causes the energization of decoding relays A8HTFP and A8H, these relays picking up and holding their front contacts closed. Relay 7CTP is now controlled at the 120 code rate, contacts *a* of transmitter 120CT being selected over back contact *b* of relay A8DTFP and front contact *a* of relay A8H.

The code transmitted westward through section 7-8T is now of the 120 code rate and the operation of relay 8TR changes to follow the new rate. With relay 8TP energized at 120 frequency, its contact *c* alternately closes front and back contacts, causing the energization of relay 8HTFP and subsequently the energization of relay 8H. The circuit over front contact *b* of relay 8H and back contact *b* of relay 8DTFP energizes the yellow lamp of signal 8G and the signal thus displays an approach indication. The closing of front contact *a* of relay 8H selects the 180 code rate for controlling transmitter repeater relay A7CTP so that master code pulses transmitted westward are changed to this frequency. The resulting change in the operation of relay 10TR causes, as will be evident, a change in the energized condition of the decoding relays, so that signal 10G now displays a clear indication, its green lamp being lighted over front contacts *b* of relays 10H and 10DTFP. Relay 8HP picks up to repeat the energization of relay 8H and opens its back contact *a* to deenergize stick relay 8S which releases. However, the code transmitter repeater relay A7CTP is already controlled over another circuit and the release of the stick relay has no effect on the coding action at this time. However, the closing of back contact *c* of relay 8S completes the circuit for energizing relay A7H and this relay picks up to complete the decoding of the reverse code being received from the west through section 8-10T. The closing of front contact *a* of relay A7H completes the circuit for permitting relay 8RC to follow the coding action of relay 8TP and the periodic operation of contact *b* of relay 8RC transmits the reverse code pulses eastward through section 7-8T. This reverse code has a positive polarity as selected over front contact *b* of relay A7DTFP and back contact *b* of relay A7HTFP.

Relay 7TR (Fig. 1D) follows this positive polarity reverse code, its normal armature being responsive and in a manner previously described, relays 7DTFP and 7H are energized to decode the reverse code pulses. This energizes the green lamp of signal 7G over an obvious circuit and the signal thus displays a clear indication for westbound moves. With front contact *c* of relay 7H closed, the control of relay A8CTP is shifted from contacts of

code transmitter 75CT to contacts of code transmitter 180CT and the master code transmitted eastward through section 5-7T is changed to the 180 code rate. Operation of relay 5TR at this new code rate causes the energization, 5 through the decoding circuit network, of relays 5DTFP and 5CD in the previously explained manner. This is followed by the energization of relay 5H over front contacts *a* of relays 5DTFP and 5CD. Signal 5G thus displays a clear indication, its green lamp being energized 10 over an obvious circuit. It is to be noted that relay 5CD of the decoding combination may be picked up first when 75 code rate pulses are originally received as the train initially clears section 5-7T. However, this pickup of relay 5CD is immaterial to the operation of the system. 15 It is to be further noted that, at this time, the reverse code transmitted as a result of the operation of relay 5RC is still of a negative polarity so that there is no change in the code being transmitted westward towards the location of signal 8G and this signal remains at the approach 20 indication.

When the train clears section 3-6T, that is, leaves completely station Z, master code at the 75 code rate is received through section 3-6T and operates relay 6TR. However, 75 code operation of relays 6TR and 6TP does 25 not affect the decoding circuit arrangement since contacts *c* of these two relays are mechanically tuned to other code rates and thus do not operate. The three decoding relays remain released at this time and there is yet no change in the released condition of relay 6DP which causes negative 30 polarity reverse code to be transmitted westward. Referring to Fig. 2, when the train is completely past the westbound signal 1G, the master code transmitted westward is at the 75 code rate similar to the action caused in section 7-8T when the eastbound train cleared past 35 signal 7G. However, referring to Fig. 1A, it will be noted that, if pulses at 75 code rate are received by relay 12TR, relay 12CD is energized and picks up, transferring the control of relay 11CTP to transmitter 120CT so that master code in the section to the west changes to the 120 40 code rate. Similar action occurs at the east end of station Z so that, after the train has cleared past signal 1G, 120 code rate pulses are received through section 3-6T by relay 6TR. The repeating operation of relay 6TP at the 120 code rate causes relay 6HTFP to become energized 45 followed by relay 6H and these two relays pick up. Signal 6G thus changes to the yellow aspect or approach indication at this time. However, relay 6DP remains deenergized since its circuit is open at front contact *c* of relay 6DTFP.

50 After the train has moved east of signal 2G (Fig. 2), code pulses at the 180 code rate are received through section 3-6T resulting in the energization of relay 6DTFP rather than relay 6HTFP, changing the indication of signal 6G to clear. Also, relay 6DP is energized at this time 55 and picks up to pole-change the track circuit connections to battery 5TB so that the reverse code in section 5-7T is now of a positive polarity. The resulting change in the energized combination of the decoding relays at signal 7G transfers the master code in section 7-8T to the 180 code 60 rate. At the west end of section 7-8T, this code rate change transfers the decoding relay arrangement to control signal 8G to display a clear indication. The apparatus for the single track stretch between stations X and Z is now returned to its normal at-rest condition as shown 65 in the various parts of Fig. 1 and the system is now ready to permit a train movement in the opposite direction if desired.

It is now assumed that a westbound train approaches 70 through the main track of station Z. It is obvious from Fig. 2 that signal 6G is in its stop position and has been for some time as the train approached, specifically, since the train passes westbound distant signal 1G in approach to station Z. Further, with relay 6DP released, the reverse code in section 5-7T is of negative polarity, which results 75 in the master code in section 7-8T being of the 120 code

rate. Signal 8G thus displays an approach indication, which is confirmed by the diagram of Fig. 2. As this train passes signal 5G displaying a green aspect and shunts the rails of section 5-7T, relay 5TR is deenergized and ceases to follow the code pulses from the west. This is followed by the deenergization of relays 5TP and 5RC in order. Likewise, relays 5DTFP and 5CD release since they are deenergized due to the nonoperation of the code following contacts of relays 5TR and 5TP. Their release is followed shortly by release of relay 5H, deenergized by the opening of front contacts *a* of the other decoding relays. The red lamp of signal 5G is now energized over back contact *b* of relay 5H. The release of relay 5CD to open its front contact *b* interrupts the energizing circuit for relay 6RC so that it cannot subsequently follow the code operation of relay 6TP. The opening of front contact *a* of relay 5H deenergizes relay 5HP which releases to pole-change the connections from battery 6TB to the track circuit.

At the location of signal 7G, relay A8TR is deenergized by the shunt on the track section and ceases to follow code, all its contacts remaining released with back contacts closed. Relays A8HTFP and A8H release shortly in order, relay A8DTFP having previously released when the reverse code was pole-changed. This transfers the control of relay 7CTP to code transmitter 75CT, the selection being made over back contact *a* of relay A8H, the circuits further including contacts *a* of transmitter 75CT and back contacts *an* and *ar* of relay A8TR. At this time, there is no change in the control circuits for relay A8CTP and this relay continues to operate at the 180 code rate.

With relay 7CTP operating at the 75 code rate, relay 8TR at signal location 8G is energized by the transmitted code pulses and now follows the 75 code rate. Contact *c* of relay 8TP ceases to operate, since it is tuned to follow only the 120 code rate, and relay 8HTFP is deenergized and shortly releases. The opening of front contact *a* of this relay interrupts the circuit for relay 8H and it likewise releases at this time. Relay 8DTFP remains released since contact *c* of relay 8TR is also inoperative at the 75 code rate. Relay 8HP releases after the expiration of its slow release period, deenergized by the opening of front contact *c* of relay 8H. Signal 8G is operated to its stop position, the red lamp being energized over an obvious circuit including back contact *b* of relay 8H. Relay 8TP follows the coding action of relay 8TR and its front contact repeater relay 8TFP remains energized. Relay 8RC likewise follows the coding operation and continues to transmit a reverse code of positive polarity, the code rate being immaterial to the operation of the system. Signal 7G continues to display a clear indication since there is no change in the reverse code polarity being received by relay 7TR.

Transmitter repeater relay A7CTP is now controlled at the 75 code rate, the circuit including back contact *a* of relay 8H, back contact *b* of relay 8S, contacts *a* of transmitter 75CT, and at times back contacts *an* and *ar* of relay A7TR. The master code transmitted westward through section 8-10T thus changes to the 75 code rate. Since the section is unoccupied at present, relay 10TR is energized by these pulses and operates at the same code rate, its contacts controlling the operation of relay 10TP at the 75 code rate also. Relay 10TFP remains energized since it repeats the operation of relay 10TP at any code rate. However, relays 10DTFP and 10H release at this time since the decoding circuit arrangement for the master code at this location is responsive only to the 180 and 120 code rates, contacts *c* of relays 10TR and 10TP being tuned, respectively, to these higher code rates. Signal 10G changes from the clear to the stop indication, the red lamp being lighted by an obvious circuit over back contact *b* of relay 10H. Relay 10HP is also deenergized by the opening of front contact *c* of relay 10H and releases at the termination of its slow release period. The coding action of relay 10RC, as

controlled by front contact *a* of relay 10TP, continues since the remainder of the energizing circuit remains intact at this time. Reverse code of positive polarity continues to be transmitted eastward through section 8-10T and maintains the existing condition of the code repeating apparatus at the location of signal 8G. There is thus no change in the reverse code transmitted eastward to the location of signal 7G and this latter signal remains in its clear position.

With relays 10H and 10S released, code transmitter repeater relay 9CTP is controlled by transmitter 75CT. This control is established over back contact *a* of relay 10H and back contact *b* of relay 10S. The master code transmitted westward through section 9-12T is thus at the 75 code rate and track relay 12TR operates at this rate followed directly by relays 12TP and 12RC. The decoding circuit arrangement at signal 12G is only partially responsive to operation at this 75 code rate, contacts *c* of relays 12TR and 12TP, as is obvious, being responsive individually only to selected higher code rates. Relay 12DTFP releases followed by relay 12H, relay 12CD remaining energized as controlled over contact *b* of relay 12TP. Signal 12G thus shifts to its stop position, the red lamp being energized over back contact *b* of relay 12H.

The reverse code transmitted by the operation of front contact *b* of relay 12RC continues to be of the positive polarity and the normal armature of relay 9TR at signal 9G follows the code. Since the rate of this code is immaterial, there is no change in the indication displayed by a signal 9G. Thus, shortly after this westbound train has passed signal 5G, the time being determined by that necessary for the cascaded action just described, signals 12G, 10G, and 8G are controlled to their stop position displaying a red aspect. All master code throughout the stretch with the exception of that being transmitted eastward by relay A8CTP at signal 7G is at the 75 code rate. It is to be remembered, of course, that the master code transmitted eastward from signal 7G is shunted by the train occupying section 5-7T. All reverse code remains the same, i.e., of positive polarity, with the westbound signals clear for the train.

At this time, relay 11CTP (Fig. 1A) is shifted in operation to the 120 code rate, the control circuit including normal and reverse contacts *b* of the relay, front contact *b* of relay 12CD, back contact *a* of relay 12H, front and back contacts *a* of transmitter 120CT, and at times back contacts *an* and *ar* of relay 11TR. If we now assume that Fig. 1E is placed to the left of Fig. 1A, so that the main track section through station X is complete, relay 6TR now follows the 120 code rate and relay 6TP directly repeats this code operation. Relay 6DTFP releases and 6HTFP is energized since contact *c* of relay 6TP, which is operating at the 120 code rate, is responsive to alternately close its front and back contacts. Relay 6H holds energized. Thus, signal 6G is controlled to its approach position, the yellow lamp being energized over front contact *b* of relay 6H and back contact *b* of relay 6DTFP. This action, referring to Fig. 2, occurs, of course, at the west end of station X so that signal 14G shifts to its approach position. Referring again to Fig. 1E, relay 6DP is deenergized at this time by the opening of front contact *c* of relay 6DTFP so that the former relay releases and pole-changes the reverse code being transmitted westward into section 5-7T which represents the track section to the west of station X in this description. Thus, the reverse armature of the track relay at the far end of the track section follows the coded action and the HTFP relay picks up, the DTFP relay releasing and the H relay holding. Using Fig. 1D as a specific example, transmitting relay 7CTP would be shifted to the 120 code rate so that signal 8G would obviously shift to its approach position. In other words, using the circuits shown as representatives of

those west of station X, it is obvious that the distance signal to the rear of signal 14G, referring to Fig. 2, also occupies the approach position so that with signal 12G at the stop indication, the two signals to the rear which control the movement of an eastbound train display an approach indication.

Although the code transmitted west into the next two track sections westward from signal 11G is changed, as described in the preceding paragraph, there is no change in the control, as an example, of relay A8CTP in Fig. 1D representing a similar relay west of station X, so that relays 5DTFP, 5H, and 5CD would hold energized and signal 5G would remain in its clear position. The reverse code transmitted by relay 6RC, repeating the operation of relay 6TP, remains of the positive polarity so that the normal armature of track relay 11TR follows the reverse code. There is thus no change at this time in the condition of the decoding relay arrangement and signal 11G remains in its clear position, the green lamp being lighted as indicated.

Returning to station Z, when the westbound train clears section 3-6T, relay 6TR resumes its code following operation. If assumed, for purposes of this description, that there is no following train, the code pulses are at the 180 code rate. Relays 6DTFP and 6H are thus energized by the decoding arrangement, as previously described, and signal 6G is controlled to its clear position, the green lamp being energized as shown. However, relay 6RC remains deenergized since its circuit is open at front contact *b* of relay 5CD, which is deenergized with the train occupying section 5-7T. Thus, no reverse code is transmitted eastward through the main track section at station Z and the track relay at the eastern end of this section remains inoperative and signal 3G (Fig. 2) remains at the stop position.

As the train approaches signal 7G, series approach relay 7A is eventually sufficiently energized to follow the code pulses. Relay 7AP is periodically energized and picks up to hold its front contacts closed in a manner previously described. As the train passes signal 7G, which is displaying a clear indication, series approach relay 7AA immediately follows the code pulses being transmitted by relay 7CTP into the rails. As a result, repeater relay 7AAP picks up and holds its front contacts closed. Relay 7TR is, of course, deenergized by the shunt across the rails of section 7-8T and releases to hold its back contacts closed. This is followed by the release of relays 7DTFP and 7H in order. Signal 7G is thus controlled to its stop position with the red lamp energized. Prior to the release of relay 7H, the circuit is complete for energizing directional stick relay 7S. This circuit is traced from terminal B over front contact *a* of relay 7AP, front contact *a* of relay 7AAP, front contact *a* of relay 7H, and the winding of relay 7S to terminal N. The closing of front contact *a* of relay 7S completes an initial stick circuit for this relay. The final stick circuit is completed by the closing of back contact *a* of relay 7H when it eventually releases and relay 7S is thus held energized as long as home relay 7H remains released.

At the west end of section 7-8T, the shunt of the rails by the train deenergizes relay 8TR and it remains with its back contacts closed. Relays 8TP and 8RC are likewise deenergized by the halting of the code following action of the track relay. Front contact repeater relay 8TFP is deenergized when contact *b* of relay 8TP remains released and relay 8TFP shortly releases. Since relays 8DTFP, 8HTFP, 8H, and 8HP are already released due to the master code being at the 75 code rate, there is no further change in the decoding arrangement at this location.

At this time, the control circuit for relay A8CTP at signal 7G is shifted to the 120 code transmitter. This selection is made over back contact *c* of relay 7H and front contact *b* of stick relay 7S, the remainder of the

circuit including front and back contacts *b* of transmitter 120CT and at times back contacts *an* and *ar* of relay 8TR. When the train clears section 5-7T, master code at the 120 rate is transmitted eastward through the section so that relays 5TR, 5TP, and 5RC operate at this code rate. Contact *c* of relay 5TP is responsive to the 120 code rate to alternately close its front and back contacts so that the decoding circuit arrangement is effective to energize relays 5H and 5CD, which pick up and hold as the decoding action continues. This completes a circuit for energizing the yellow lamp of signal 5G over front contact *b* of relay 5H and back contact *b* of relay 5DTFP so that the signal displays an approach indication for a following train.

The energizing circuit for relay 6RC is now complete at front contact *b* of relay 5CD and relay 6RC repeats the code following operation of relay 6TP. Reverse code is now transmitted eastward through section 3-6T. Since relay 5HP is obviously energized over front contact *a* of relay 5H, the reverse code is of positive polarity. Using Fig. 1A to represent the east end of section 3-6T, it is obvious that the normal armature of relay 11TR will operate to follow this positive reverse code. Relays 11DTFP and 11H are energized and pick up so that signal 11G, which represents signal 3G in Fig. 2, is shifted from its stop to clear position, the green lamp being energized over a previously traced circuit. It is to be noted that this signal thus displays no approach indication at any time for a following move, operating directly from its stop to its clear indication. With relay 11DP now picked up, referring again to Fig. 1A, since front contacts *a* and *c* of relays 11H and 11DTFP, respectively, are closed, the reverse code transmitted eastward from this location changes to the positive polarity so that the distance signal for westbound moves, signal 1G in Fig. 2, is controlled to its clear indication from the approach indication, that is, from the yellow aspect to the green aspect.

Returning now to Fig. 1E, the location of signal 5G, which is now receiving master code from the west at the 120 code rate, as previously described, relay 5RC operates to transmit the reverse code westward through the section, the polarity being positive since relay 6DP is energized and picked up. The normal armature of relay 8TR thus follows this reverse code so that the decoding arrangement operates to energize relay 8ADTFP, since relay 7AP is now released and its back contact *b* closed. However, relay 8AH remains deenergized since its energizing circuit is interrupted at back contact *c* of relay 7S, which is held energized by its stick circuit. Thus relay 7CTP remains controlled by transmitter 75CT over back contact *a* of relay 8AH and there is no change in the master code being transmitted into the rails of section 7-8T which are presently shunted by wheels and axles of the westbound train.

As this westbound train passes the location of signal 8G, it shunts the rails of section 8-10T. Relay 8TR ceases its code following operation and remains with its back contacts closed. Since master code continues to be transmitted into the rails, relay 8A immediately follows this code and its repeater relay 8AP picks up and holds. With relay 8TR inoperative and back contact *b* of relay 8AP open, the decoding circuit arrangement is deenergized at this location and relays 8ADTFP and 8AH release. Under these conditions, however, relay 8S is not energized, even though front contact *a* of relay 8AP and back contact *b* of relay 8TFP are closed, since relay 8HP is released and its front contact *a* thus open, interrupting the energizing circuit for relay 8S as is proper for a westbound train. Thus, at this time, there is no change in the control circuit for relay 8TR and this relay continues to follow the 75 code rate as controlled by transmitter 75CT.

Also at this time, relay 10TR is deenergized by the train shunt and halts its code following operation. Re-

lays 10TP and 10RC are likewise deenergized as a result and the transmission of reverse code eastward through this section is halted. The opening of front contact *b* of relay 10TP deenergizes relay 10TFP so that this latter relay shortly releases. The remaining decoding relays associated with relay 10TR are already released since the decoding arrangement is nonresponsive to code operation at the 75 code rate. Thus these relays released, as previously described, shortly after the west-bound train entered the single track stretch. With the release of relay 10TFP, the circuit is established to control relay 10RC by code transmitter 120CT. This circuit extends from terminal B over front contact *c* of relay 9H, this relay being picked up at this time, back contact *b* of relay 10TFP, front contact *b* of transmitter 120CT, and the winding of relay 10RC to terminal N. The periodic closing of front contact *b* of relay 10RC at this code rate transmits a master code eastward through section 8-10T. The track circuit at this time may be traced from the positive terminal of track battery 10TB over back contact *e* of relay 10TFP, the winding of relay 9A, and front contact *a* of relay 9H to one rail of the track section, returning from the other rail over back contact *a* of relay 10TR, front contact *b* of relay 10RC, and back contact *b* of relay 9S to the negative terminal of track battery 10TB. These master code pulses are, of course shunted by the wheels and axles of the approaching train, although the current flow initially is insufficient to energize relay 9A for code following operation.

When the train clears section 7-8T, master code at the 75 code rate is received from the eastern end of the section and relay 8TR operates to follow the code pulses. Relay 8TP repeats this code following operation but relay 8RC remains deenergized since its circuit is interrupted at front contact *a* of relay A7H, this relay being deenergized at this time. In addition, the track circuit for transmitting reverse code eastward through the track section is open at front contacts *b* of relays A7HTFP and A7DTFP. The decoding relays associated with relay 8TR remain in their released position since the decoding circuit arrangement is nonresponsive in its entirety to code pulses at the 75 code rate. Thus, signal 8G remains in its stop position with the red lamp energized. The operation of relay A7CTP remains controlled by code transmitter 75CT since relay 8H is still released. As the train continues westward, relay 8A eventually ceases operation and its repeater relay 8AP releases.

As the train approaches signal 9G, relay 9A is eventually sufficiently energized by the master code being transmitted eastward from this location to follow the code pulses. It is to be remembered that this master code is transmitted by relay 10RC, which under these special conditions is controlled over contact *b* of transmitter 120CT, as previously described. Relay 9AP, energized periodically over front contact *a* of relay 9A, picks up and holds its front contacts closed. As the train passes signal 9G, it shunts the rails of section 9-12T so that relay 9TR is deenergized and ceases to follow code pulses. This results in the deenergization of relays 9DTFP and 9H which then release shortly. This controls signal 9G to its stop indication, the red lamp being energized. Also as the train enters section 9-12T, relay 10A follows the pulses of the master code being transmitted by relay 9CTP and, as a result, relay 10AP is periodically energized and picks up, remaining with its front contacts closed. Prior to the release of relay 9H at the end of its release period, a circuit is established for energizing relay 9S. This circuit may be traced from terminal B at back contact *a* of relay 10HP over front contact *a* of relay 9AP, front contact *a* of relay 10AP, front contact *d* of relay 9H, back contact *c* of relay 10S, and the winding of relay 9S to terminal N. The closing of front contact *a* of relay 9S bypasses

front contact *d* of relay 9H to provide an initial stick circuit. Upon the release of relay 9H, the final stick circuit for relay 9S is established including back contact *d* of relay 9H, front contact *a* of relay 9S, and back contact *c* of relay 10S. Relay 9S is thus held energized until relay 9H again picks up to open its back contact.

With the rails of the track section shunted, the operation of relay 12TR also halts and this, of course, is followed by the deenergization of relays 12TP and 12RC. 10 Relay 12CD is likewise deenergized when the operation of contact *b* of relay 12TP halts and relay 12CD shortly releases. The closing of back contact *b* of relay 12CD shifts the control of relay 11CTP from transmitter 120CT to transmitter 75CT so that the master code transmitted 15 westward in section 11-14T is now at the 75 code rate. Relay 14TR, which would be located at the west end of station X, and which may be represented by relay 6TR in Fig. 1E, now follows the pulses of the 75 code rate. This results in the release of the associated decoding relays HTFP and H since the decoding circuit, 20 which may be represented by that shown associated with relay 6TR in Fig. 1E, is nonresponsive to code operation at the 75 code rate. Signal 14G, shown in Fig. 2, is at this time controlled to its stop position, the red 25 lamp being energized. This action is obvious from an inspection of the similar circuits shown in Fig. 1E associated with track relay 6TR.

When the train clears section 8-10T, relay 10TR is energized by the master code pulses transmitted from 30 the location of signal 8G and follows this code at the 75 code rate. Relay 10TP directly repeats the code following operation and repeater relay 10TFP is energized and picks up to decode the operation. The regular decoding circuit arrangement of course, is nonresponsive 35 to the code operation of the relays at the 75 code rate and thus the decoding relays 10DTFP, 10HTFP, and 10H remain released. This decoding circuit arrangement is also interrupted at back contact *d* of relay 9S so that in any event the relays could not be energized. 40 Relay 10RC at this time repeats the code following operation of relay 10TP. However, the circuit now includes front contact *d* of relay 9S and front contact *a* of relay 10TP, since the normal control circuit for relay 10RC over front contact *b* of relay 10TFP is interrupted 45 by open front contact *c* of relay 9H. The reverse code transmitted at this time is of the negative polarity. This circuit may be traced from the positive terminal of battery 10TB over front contact *d* of relay 10TFP, front contact *b* of relay 9S, front contact *b* of relay 50 10RC which is periodically closed, and back contact *a* of relay 10TR to the (-) rail of the track section, returning from the (+) rail over back contact *a* of relay 9H to the negative terminal of battery 10TB. The polarity applied to the rails over this circuit is obviously the reverse of that normally applied during at-rest conditions.

At the location of signal 8G, the reverse armature of relay A7TR is responsive to this negative polarity reverse code. With relay 8AP released so that its back 60 contact *b* is closed, the decoding circuit arrangement operates to energize relays A7HTFP and A7H, the circuit for relay A7H being complete since relay 8S is released. The closing of front contact *a* of relay A7H establishes the circuit to enable relay 8RC to follow the 65 coded operation of relay 8TP in the usual manner. However, the reverse code transmitted is of the negative polarity, the circuit supplying energy to the rails being traced from the positive terminal of battery 8TB over front contact *b* of relay A7HTFP, front contact 70 *b* of relay 8RC, and back contact *a* of relay 8TR to the (-) rail of the section, returning from the (+) rail over back contact *b* of relay A7DTFP to the negative terminal of the track battery. At signal location 7G, the reverse armature of relay 7TR follows the negative polarity reverse code received over the track sec- 75

tion and relays 7HTFP and 7H are energized and pick up. Signal 7G is controlled to its approach position, the yellow lamp being energized over a circuit including front contact *b* of relay 7H and back contact *b* of relay 7DTFP. The opening of back contact *a* of relay 7H also deenergizes directional stick relay 7S which releases at this time.

The control of transmitting relay A8CTP is now shifted to transmitter 180CT over front contact *c* of relay 7H, so that master code at the 180 code rate is transmitted eastward to the location of signal 5G. Track relay 5TR follows the code pulses at the 180 code rate and relay 5DTFP is now energized over front contact *c* of relay 5TR which is periodically closed at this code rate. Signal 5G changes from its approach indication to the clear indication, the green lamp being lighted over front contacts *b* in series, of relays 5H and 5DTFP. No other change occurs at this signal location.

At signal location 7G, since relay A8DTFP is already energized, the closing of back contact *c* of relay 7S completes the circuit for energizing relay A8H which picks up and holds. The opening of back contact *a* and the closing of the corresponding front contact of relay A8H shifts the control of relay 7CTP from transmitter 75CT to transmitter 180CT, since front contact *b* of relay A8DTFP is already closed. The master code transmitted westward through section 7-8T thus becomes of the 180 code rate and track relay 8TR at the west end of the section follows the new rate, as do its repeater relays 8TP and 8RC. The new code rate, of course, is immaterial to the reverse code being transmitted eastward through 7-8T since polarity only is the determining factor for such codes. Relays 8DTFP and 8H now pick up, the decoding circuit arrangement being responsive to the 180 code rate to energize these relays in the manner previously explained. Signal 8G changes to its clear position, the green lamp being energized over front contacts *b*, in series, of the two energized decoding relays. With the closing of front contact *a* of relay 8H, the control of relay A7CTP is shifted directly to transmitter 180CT and the master code transmitted westward through section 8-10T changes to the 180 code rate. Track relay 10TR increases its code following operation to the 180 code rate and this is directly reflected in repeater relays 10TP and 10RC. Again, the change in rate of the reverse code transmitted, due to the operation of relay 10RC, is immaterial to the operation of the reverse code circuits to the rear of signal 9G. Although the code rate is now proper for the energizing of decoding relays 10DTFP and 10H, the decoding circuit arrangement is still deenergized by open back contact *d* of relay 9S so that the decoding relays remain released and signal 10G remains in its stop position. It is to be noted that, at this time, transmitter repeater relay 9CTP is operating at the 75 code rate, its energizing circuit being selected over back contact *a* of relay 10H and back contact *b* of relay 10S.

When the westbound train passes signal 11G, a shunt is applied to the rails of section 11-14T at station X. Relay 11TR is thus deenergized and releases all of its contacts. This causes the deenergization of relays 11DTFP and 11H which release shortly, causing signal 11G to assume its stop position with the red lamp energized. With the two decoding relays released, the circuit for relay 11DP is interrupted and this relay also releases at this time. Relay 11CTP is already controlled to follow the 75 code rate and the only change at the west end of station X is the deenergization of track relay 14TR, not shown herein, but represented by relay 6TR on Fig. 1E. However, since signal 14G, shown in Fig. 2, is already occupying its stop position, there is no material change in the conditions at the west end of station X.

When the train clears section 9-12T, relay 12TR is energized and follows the master code pulses at the 75

code rate. Relays 12TP and 12RC repeat this code following operation directly. Operation of contact *b* of relay 12TP between its front and back positions energizes relay 12CD, in the manner previously described utilizing capacitor C1, and this relay picks up and holds its front contacts closed. The opening of back contact *b* and the closing of the corresponding front contact of relay 12CD transfers the control circuit for relay 11CTP from transmitter 75CT to transmitter 120CT so that the master code transmitted into section 11-14T now increases to the 120 code rate. However, since the rails of the section are shunted, no action results from this change in the code rate at this time. Periodic closing of front contact *b* of relay 12RC transmits reverse code eastward through section 9-12T, the polarity being negative since relay 11DP is released so that the track battery connections are over back contacts *a* and *b* of relay 11DP.

At location of signal 9G, the reverse armature of track relay 9TR follows the negative polarity reverse code. With back contact *b* of relay 10AP closed at this time, relays 9HTFP and 9H are energized by the decoding arrangement and pick up. With front contact *b* of relay 9H and back contact *b* of relay 9DTFP closed, the yellow lamp of signal 9G is energized and the signal thus displays its approach indication. The opening of back contact *d* of relay 9H interrupts the stick circuit for relay 9S and this relay, thus deenergized, releases. The release of relay 9S to close its back contact *d* completes the circuit for supplying energy to the decoding circuit arrangement associated with track relay 10TR. Since this track relay is following pulses at the 180 code rate, relays 10DTFP and 10H are energized at this time and pick up. Signal 10G thus operates to its clear position, the green lamp being energized over front contacts *b*, in series, of the two energized decoding relays. Relay 10RC continues to follow the operation of front contact *a* of relay 10TP since the energizing circuit interrupted at front contact *d* of relay 9S is replaced by the usual energizing circuit over front contact *b* of relay 10DTFP and front contact *c* of relay 9H.

The closing of front contact *a* of relay 10H transfers the circuit controlling relay 9CTP to contacts of transmitter 180CT and the master code transmitted westward through the track section 9-12T resumes its 180 code rate. The change in the code following operation of relay 12TR to the 180 code rate causes its front contact *c* to periodically close so that relay 12DTFP is energized and picks up. The closing of front contact *a* of this relay completes the circuit for the remaining decoding relay 12H which picks up and is held energized over front contacts *a* of relays 12DTFP and 12CD. Signal 12G changes to its clear position its green lamp being energized over front contacts *b* of relays 12DTFP and 12H. The control of relay 11CTP is transferred to contacts *a* of transmitter 180CT by the opening of back contact *a* and the closing of front contact *a* of relay 12H.

At signal location 9-10G, with relay 9H picked up and relay 9S released, the reverse code transmitted eastward through track section 8-10T is pole-changed to the positive polarity. This circuit may be traced from the positive terminal of track battery 10TB over front contact *e* of relay 10TFP and front contact *a* of relay 9H to the (+) track connection, returning from the (-) rail connection over back contact *a* of relay 10TR, front contact *b* of relay 10RC, and back contact *b* of relay 9S to the negative terminal of the battery. Relay 10TR changes its operation from the reverse armature to the normal armature with this positive polarity of the reverse code. Relay 10HTFP is thus deenergized and releases. As soon as back contact *c* of relay 10HTFP closes, relay 10DTFP is immediately energized and quickly picks up to decode the positive polarity reverse code. The reversal of the positions of contacts *b* of relays 10HTFP and 10DTFP pole-changes the polarity of the reverse

code being transmitted eastward through track section 7-8T, these contacts now being closed as shown in the drawings so that the track circuits initially traced from track battery 8TB are again effective. The rapid transfer by contacts *b* of relays A7HTFP and A7DTFP between the two track circuit connections prevents any loss of reverse code pulses during the pole-changing action. The operation of relay 7TR shifts from its reverse to its normal armature with this change in polarity of the reverse code and relay 7DTFP is energized while relay 7HTFP is deenergized and releases. The energizing circuit for the signal lamps is thus shifted by contact *b* of relay 7DTFP from the yellow to the green lamp and signal 7G now displays a clear indication. Since there is no loss of reverse code pulses during the pole-changing action, the shift from the yellow to the green signal aspect occurs without any intervening red flash.

When the train track section 11-14T, that is, has moved completely west of signal 13G, shown in Fig. 2, the 180 code pulses being transmitted by relay 11CTP, shown in Fig. 1A, cause relay 14TR at the west end of station X to follow at a similar rate and the decoding arrangement is such that signal 14G is controlled to its clear position. However, relay 14RC remains deenergized. Referring to a similar arrangement shown in Fig. 1E for relay 6RC, it is noted that the energizing circuit is interrupted, with the train west of station Z, while front contact *b* of relay 5CD is open. As there is no reverse code transmitted eastward through section 11-14T, there is no operation of relay 11TR and the associated decoding relays remain released. Signal 11G remains in its stop position and relay 11DP remains released so that the reverse code transmitted eastward through 9-12T remains of negative polarity. Signal 9G remains in its approach position until this westbound train clears by the next westbound signal in advance of signal 13G shown in Fig. 2. At this time, relay 14RC is energized since its circuit is completed and reverse code having positive polarity is transmitted eastward so that signal 11G is controlled to its clear position. Relay 11DP picks up since the decoding relays 11H and 11DTFP have picked up, closing their front contacts *a* and *c*, respectively. Reverse code transmitted eastward by relay 12RC thus becomes of positive polarity and decoding relay 9DTFP is energized in place of relay 9HTFP so that the green lamp of signal 9G is now energized. Signal 9G is thus controlled to its clear position at the same time that relay 11G is similarly positioned.

The apparatus in the system for the stretch of single track shown in the various parts of Fig. 1 is now returned to its normal at-rest position as shown in the drawings. It is believed that the action of the apparatus for a closely following train movement in either direction is obvious from the previous description of the system operation during the passage of the train in each direction through the stretch, when taken in connection with the drawings including Fig. 2. Therefore, such an operational description of the apparatus is not included in this application in order to simplify the specification. It is to be noted at this time that with either direction of train movement, the signals for the opposing direction immediately behind the train are held in their stop position with red lamps energized. In addition, the directional stick relays at the intermediate signals are energized and pick up only as the train passes the signal, that is, only as the train occupies both the track section to the rear and the track section in advance of this intermediate signal in question.

The system of our invention includes specific checks for protection against overrunning of signals and for overlap at the intermediate signals which, of course, have been described in connection with the movement of the train through the single track stretch but which were not particularly emphasized. For example, considering the staggered signal locations 7G and 8G, back contact *c* of directional stick relay 7S is included in the energizing cir-

cuit for decoding relay A8H shown in Fig. 1D. Thus, any time that relay 7S is energized, relay A8H cannot be energized due to the open back contact of the stick relay. With relay A8H deenergized, the master code transmitted westward through section 7-8T to control, through relay 8TR and its associated decoding relays, the indication displayed by signal 8G cannot be higher than the 75 code rate since the control circuit for relay 7CTP over back contact *a* of relay A8H selects the contacts of transmitter 75CT. Thus signal 8G is held at the stop indication immediately behind a westbound train. This condition, of course, continues until the westbound train passes the next signal in advance, signal 9G, since relay 7S is maintained energized by its stick circuit until both sections 8-10T and 7-8T have been cleared by the westbound train. Signals 8G and 5G thus cannot simultaneously display approach indications. Likewise, since the master code received at signal 8G under these conditions is of the 75 code rate, the master code transmitted westward to signal 10G and from that to signal 12G is likewise at the 75 code rate so both of these opposing signals, that is, 10G and 12G, are held in the stop positions. This condition exists any time that relay 7S is picked up, whether correctly or incorrectly. Without this check, relay 7S may inadvertently be energized so that an eastbound train passing headblock signal 12G will not cause the opposing headblock signal 5G to display a stop indication. This condition results since relay A8CTP, with relay 7S having its front contact *b* closed, is energized at the 120 code rate so that signal 5G would display an approach indication. Thus, without such a check, the eastbound train could advance as far as intermediate signal 8G, which would be displaying an approach indication, at about the same time a westbound train might pass signal 5G, also displaying an approach indication. Such an occurrence is prevented by the circuit arrangements of our invention. In addition, including back contact *b* of relay 7AP in the decoding circuit arrangement associated with relay A8TR provides that any condition which may initiate the energization of directional stick relay 7S immediately results in opposing signals 10G and 12G, as well as 8G with the normal stagger shown in Fig. 1, displaying a stop indication. The insertion of front contact *a* of relay 10TFP, Fig. 1B, into the control circuit for relay 10H produces an identical result at this location.

With the circuit arrangement shown for the system of our invention, the position of any outlying switch is checked by the use of a conventional shunting circuit. That is, if the switch occupies any position other than its normal position, the rails of the track section are shunted through contacts of the switch contactor closed in all but the switch normal position. When such a hand-throw, switch is operated, it is desirable that all opposing signals display their most restrictive indication and all signals leading away from the switch display proceed indications so that the train may travel in either direction. Thus, after a train entering the main line over such a switch has moved by an intermediate signal location, the direction in which it is moving is established by energizing a directional stick relay which will result in proceed indications being displayed by signals to the rear to permit a following train movement.

In the advance pickup type circuit used in our invention for the directional stick relays, the combination by which the two track circuits control these relays produces this switch position check without controlling the circuits for the directional stick relays over normal position contacts of such outlying switches. For example, if an outlying switch is located in the track section 8-10T, reversing this switch to shunt the rails halts the flow of code in both directions in this track section. The shunting of the master code flowing westward causes the release of relay 10TR with the resulting release of the decoding relays then energized. Signal 10G is controlled to its stop position. However, signal 9G would continue to display a

proceed indication for the westbound move, since the reverse code received from the west end of track section 9-12T is not affected as to polarity so that no change occurs in the decoding circuit arrangement associated with track relay 9TR. Of course, since relay 10S is not at this time picked up, relay 9CTP is controlled over contacts of transmitter 75CT so that signal 12G displays a stop indication. With relay A7TR at the east end of section 8-10T deenergized, so that the associated decoding relays including relay A7H release, the circuit controlling 8RC is interrupted at front contact *a* of relay A7H. As the transmission of reverse code eastward through section 7-8T is interrupted, signal 7G displays its stop indication. Relay A8CTP is then controlled, over back contact *c* of relay 7H, by contacts of transmitter 75CT and signal 5G also changes to its stop position since only relay 5CD remains energized at that location. However, the transmission of reverse code westward through section 5-7T is unaffected by this change in code rate and, since relay 7S is deenergized so that relay A8H remains energized, relay 7CTP is still controlled over contacts of transmitter 180CT and signal 8G remains in its clear position.

If this train entering at the midpoint of the section moves westward, as it passes signal 9G, occupying simultaneously track sections 9-12T and 8-10T, stick relay 9S is energized in the manner previously described and the westbound direction is established. As soon as this train clears section 8-10T, signal 7G would be controlled, in the manner previously described, to its approach indication and signal 5G to its clear indication. If the train moves eastward, directional stick relay 8S will be energized as it passes signal 8G and the eastbound direction will be established. As soon as the train then clears section 8-10T, signal 10G is controlled to its approach indication and following trains may proceed through the stretch.

We have pointed out, therefore, in the description of the system of our invention, several advantages which result in an economical signal system for single track railways, the system being of the A.P.B. type utilizing normally energized coded track circuit without any line control wires. The use of mechanically tuned frequency responsive code following relays, to provide both decoding of the frequency code and transmission of the reverse code, results in an efficient and economical use of relays. Advance type pickup for the directional stick relays, in connection with two track circuit control, results in a safe system providing checks against the overrun of intermediate signals and overlap protection between such signals in the event of inadvertent operation of such stick relays. In addition, checks of the position of outlying switches and an establishment of traffic direction for trains entering the main line at such switches is efficiently and effectively controlled.

Although we have herein shown and described but one form of the apparatus and circuit arrangement embodying the A.P.B. signaling system of our invention, it is to be understood that various changes and modifications may be made therein within the scope of the appended claims without departing from the spirit and scope of our invention.

Having thus described our invention, what we claim is:

1. In a coded track circuit signaling system, the combination comprising, a stretch of railway track comprising adjoining first and second electrically isolated track sections, first and second series approach relays and batteries at the juncture of said track sections for said first and second sections respectively; means for supplying coded energy through the winding of each said approach relay from each respective battery to the rails of each respective track section, the windings of said relays being so proportioned that said coded energy is of a value to pick up each respective relay when and only when each respective track section is occupied by a train within a predetermined distance of said juncture; means at

the end of said first track section remote from said juncture for supplying coded energy to the rails of said track section during the off periods of the coded energy supplied to the rails of the section at said juncture, a code following track relay at said juncture, means for supplying the coded energy supplied to the rails of said first track section at said remote end to the winding of said code following relay during the said off periods of said coded energy supplied to the section at said juncture, a slow release relay, means controlled by said code following relay for picking up said slow release relay when said code following relay is following said pulses of energy supplied to its winding, a directional stick relay, means controlled by said approach relays and said slow release relay for picking up said stick relay when and only when both said approach relays are following pulses of coded energy and said slow release relay is picked up, and means controlled by said slow release relay for maintaining said stick relay picked up when once picked up provided said slow release relay is thereafter released.

2. At the juncture of electrically isolated adjoining first and second track sections in a coded track circuit signaling system, the combination comprising; means for supplying normal pulses of energy to the rails of said first and second sections through the windings of first and second series approach relays respectively, said pulses of energy being effective to pick up said relays when and only when each respective track section is occupied by a train within a predetermined distance of said juncture; means at the end of said first track section remote from said juncture for supplying coded energy to the rails of said track section during the off periods of the normal pulses of energy supplied to the rails of the section at said juncture, a code following relay connected to the rails of said first section at said juncture during the off periods of said normal pulses of energy for receiving from the rails of said section said reverse pulses of energy supplied to the rails of the section at the opposite end thereof during the said off periods of the normal pulses of energy, a first slow release relay, means controlled by said code following relay for picking up said slow release relay when said code following relay is following said reverse pulses of energy, a first and second slow release repeater relay for said first and second approach relays respectively, means controlled by said approach relays for picking up each respective repeater relay when its respective approach relay is following said normal pulses of energy, a directional stick relay, a pickup circuit for said directional stick relay including in series a front contact of each said slow release repeater relay and a front contact of said first slow release relay, and a stick circuit for said stick relay including a back contact of said first slow release relay.

3. At an intermediate signal location in a coded track circuit signaling system for a single track stretch of railway provided with first and second electrically isolated track sections extending in opposite directions from said location, a signal for governing train movements from said first track section into said second track section, means for supplying normal pulses of coded energy to said first and second track sections at said signal location, means for supplying reverse pulses of coded energy to said second track section at the end remote from said signal location and during the off periods of said normal pulses, means responsive to normal pulses of energy flowing in said first section and operating to close a first contact only when a train occupies the first section within a predetermined distance of said signal, means responsive to normal pulses of energy flowing in said second section and operating to close a second contact only when a train occupies the second section within a predetermined distance of said signal, means responsive to reverse pulses of energy flowing in said second section and operating to close a third contact only when the second section is unoccupied by a train and to close a fourth contact a pre-

determined time interval after the second section is occupied by a train, a directional stick relay; a pickup circuit for said directional stick relay including said first, second and third contacts, and a stick circuit for said relay including one of its own front contacts and said fourth contact.

4. In a coded track signaling system for a stretch of railway track provided with two electrically isolated track sections having a juncture, the combination comprising, a series approach track relay for each said section adjacent said juncture, means for energizing each said approach relay when a train occupies the associated

section within a predetermined distance of said juncture, a slow release relay, means for energizing said slow release relay when one of said sections is unoccupied, a directional stick relay, means controlled by said approach relays and said slow release relay for energizing said directional stick relay when said approach relays and slow release relay are energized, and means controlled by said slow release relay and said directional stick relay for maintaining said stick relay energized when said slow release relay is deenergized.
